SHEET FEEDING MACHINE

Ross Meredith, Pearl River, N. Y., assignor to
 Dexter Folder Company, New York, N. Y., a
 corporation of New York

Application July 30, 1932, Serial No. 626,906

94 Claims. (Cl. 271—12)

This invention relates to sheet feeding mechanism, and while capable of general use, is particularly adapted to feed sheets of material to a printing press or other sheet receiving means.

5 One object of this invention is to provide improved mechanism which feeds sheets one after another either in a substantially continuous manner, or any desired timed relation, to the printing press or other sheet receiving means to 10 be fed.

Another object of this invention is to provide mechanism embodying a novel arrangement and association of pack advancing, sheet separating, and sheet conveying instrumentalities which 15 operate with each other to feed the sheets successively to the sheet receiving means.

Another object of this invention is to provide improved mechanism of the type above referred to, which supports and advances a pack of sheets 20 standing on edge one behind another, and enables each sheet to be forwarded from its standing position and advanced for delivery to the sheet receiving means.

Another object of this invention is to provide 25 improved mechanism which is constructed and operated to feed sheets of tin or other metal or other stiff materials, efficiently and with great rapidity to means for operating upon such sheets.

30 Another object of this invention is to provide a sheet feeder of the type wherein the sheets stand on edge one behind another and which enables the supply of sheets thereon to be replenished without stopping said feeder.

35 Another object of this invention is to provide a feeder of the type wherein the sheets stand on edge one behind another, and which may be loaded, or have the supply of sheets thereon replenished, with sheets initially 40 plied to the feeder standing on edge one behind another or laying horizontally in a stack one on another.

A further object of this invention is to provide an improved pack supporting and advancing 45 mechanism of the type wherein the sheets stand on edge one behind another.

A still further object of this invention is to provide improved front stops, adjustments, and control devices, for the pack supporting and advancing mechanism.

50 Another object of this invention is to provide improved pack loading means for the pack supporting and advancing mechanism.

Another object of this invention is to provide 55 improved pack loading means enabling the pack

supporting and advancing mechanism to be re-loaded while in operation.

Another object of this invention is to provide improved sheet separating and forwarding devices that separate and advance sheets successively from a supply thereof on a feeder.

Another object of this invention is to provide improved sheet separating and forwarding devices that facilitate the separation and forwarding of sheets from a pack thereof standing on 65 edge one behind another.

Another object of this invention is to provide improved sheet separating and forwarding devices which are operated so that they will not interfere with advancing movements of sheets 70 by conveying mechanism to which the sheets are delivered.

Another object of this invention is to provide improved sheet separating and forwarding devices which may be rocked inwardly and outwardly of opposed margins of a sheet to facilitate separation thereof from a supply and to insure advancing movement of said sheet by the sheet conveying mechanism.

Another object of this invention is to provide 80 sheet separating and forwarding devices of the suction type with improved means for making and breaking the vacuum therein.

Another object of this invention is to provide 85 improved sheet separating and forwarding devices of the suction type operated and controlled so that the vacuum may be made and broken therein to facilitate separation and forwarding of sheets from a pack thereof standing 90 on edge one behind another.

Another object of this invention is to provide 95 improved sheet separating and conveying mechanisms which are constructed, operated, and associated so that sheets standing on edge one behind another may be separated and conveyed for delivery to sheet receiving means.

Another object of this invention is to provide 100 improved sheet conveying mechanism which has cooperating stationary and movable curved portions that enable the sheets to be turned while being advanced by said mechanism.

Another object of this invention is to provide 105 improved sheet conveying mechanism which is of the endless type, and improved sheet supporting means on which the sheets are advanced by sheet engaging devices of the sheet conveying mechanism.

Another object of this invention is to provide 110 improved sheet conveying mechanism

- having parts that are adjustable to accommodate sheets of various widths. 80
- Another object of this invention is to provide improved mechanism for accelerating movement 5 of the sheets from the sheet conveying mechanism to the sheet receiving means. 85
- Another object of this invention is to provide improved guide means over which the sheets are advanced from the sheet conveying mechanism 10 to the sheet receiving means.
- Another object of this invention is to provide improved sheet conveying means which receives sheets from a feeder or other instrumentality and supports and advances the sheets so that 15 the surfaces thereof will not be disfigured or marred. 90
- Another object of this invention is to provide improved means for loading a feeder from the floor or foundation on which it is supported, 20 conveniently and at relatively low heights. 95
- Another object of this invention is to provide an improved method of loading a feeder either by hand or truck, and wherein the time and labor incident to loading the feeder are reduced 25 to a minimum. 100
- Another object of the present invention is to provide improved sheet feeding or handling means embodying novel devices that enable sheets to be supplied thereto and conveniently placed for registering purposes. 105
- Another object of this invention is to provide a sheet feeder which prevents the delivery of more than one sheet at a time without stopping the feeder. 110
- Another object of this invention is to provide improved pack loading means which enables a pack of sheets to be moved into position in a feeder and then dropped onto the advancing means thereof. 115
- Another object of this invention is to provide an improved feeder which enables the feeding of sheets of metal or other substances coated, printed, or impregnated and in a "sticky" or "tacky" condition. 120
- Another object of the present invention is to provide improved devices or instrumentalities for loading a supply of sheets on a feeder or other machine. 125
- Another object of the present invention is to provide improved feeder loading means having novel devices and attachments thereon for adjusting the load to any desired configuration and position. 130
- Another object of this invention is to provide improved pack holding and loading means and devices thereon for retaining the pack or load in any desired position. 135
- Another object of this invention is to provide improved pack holding and transporting means for the delivery of a pack or supply of sheets to any desired point or instrumentality. 140
- Another object of this invention is to provide improved pack holding and loading means and novel devices thereon whereby the pack or load may be quickly and conveniently transferred to the mechanism or device to receive it. 145
- Another object of this invention is to provide improved pack loading means and novel devices thereon supporting the pack or load and arranged so as to be locked in order to prevent accidental displacement of the load or pack. 150
- Another object of this invention is to provide improved pack holding and loading means with parts thereof so constructed and arranged that they may be quickly and conveniently released to deliver the load when it has been moved into position with respect to the device or instrumentality to receive it. 80
- Another object of this invention is to provide improved loading means for delivering a new supply of sheets to a feeder and constructed and arranged so as to be connected therewith and advance the diminishing supply and the new supply while parts of the feeder are being adjusted to receive and feed the new supply. 85
- Another object of this invention is to provide sheet transporting and loading devices which, when placed in position in, and connected with, a sheet receiving device, constitute the advancing mechanism for the diminishing and new supplies of sheets until replaced by the advancing mechanism of the sheet receiving device. 90
- Another object of this invention is to provide improved sheet separating means which flexes or buckles the sheet in a novel manner to separate it from the supply, and enables the sheet to be separated from the supply without carrying another sheet or sheets therewith. 95
- Another object of this invention is to provide improved sheet separating means which buckles the sheet in a novel manner and enables it to straighten out after it has been separated from the supply or front end of the pile. 100
- Another object of this invention is to provide improved sheet separating devices which, through differential motion during part of their cycle of operation and the production of buckles successively in angularly or transversely related directions, separates the sheet from the supply regardless of the character of the material or the tendency of the sheets to adhere together. 105
- Another object of this invention is to provide improved sheet separating means for a feeder of the type wherein the sheets stand on edge one behind another, and novel means for yieldingably mounting the sheet separating means. 110
- Another object of this invention is to provide improved sheet feeding means which may be thrown out of operation while an additional supply of sheets is being placed on the feeder, and then thrown into operation with respect to said supply to feed the same. 115
- Another object of this invention is to provide improved loading means and improved sheet feeding means, wherein mechanism which advances the sheets on the sheet feeding means becomes inoperative during reloading by the loading means, and advancing mechanism of the loading means is either operative or inoperative accordingly. 120
- Another object of this invention is to provide sheet transporting and loading means which, when positioned in and connected with a sheet receiving device, constitute advancing mechanism for the entire supply of sheets until replaced by advancing mechanism of the sheet receiving device. 125
- These and other objects of this invention will appear as the following description thereof proceeds and in order to more clearly understand said invention, reference may be had to the accompanying drawings which illustrate various embodiments of the inventive idea, and wherein like reference characters designate like parts throughout the several views. 130
- In said drawings:
- Figs. 1 and 1a are complementary side views of associated sheet receiving, sheet conveying, sheet separating and forwarding, and pack feed- 135

- ing and loading mechanisms embodying the present invention;
- Figs. 2 and 2a are complementary vertical longitudinal sectional views of the mechanisms shown in Figs. 1 and 1a;
- Fig. 3 is a transverse vertical sectional view, with parts omitted, on the line 3—3 of Fig. 1;
- Figs. 4 and 5 are transverse vertical sectional views, with parts omitted, on the lines 4—4 and 5—5, respectively, of Fig. 1a;
- Fig. 6 is a detail perspective view of driving means for the above mentioned mechanisms;
- Fig. 7 is a detail perspective view, with parts omitted, of the pack feeding mechanism and driving connections therefor;
- Fig. 7a is a detail perspective view of a pack holder;
- Fig. 8 is an enlarged detail perspective view of sheet stops, sheet detectors, and a link carried pawl controlled and operated by said sheet detectors;
- Fig. 9 is a vertical longitudinal sectional view of mechanism controlled by the link carried pawl and, in turn, controlling the operation of the pack feeding mechanism;
- Fig. 10 is a detail perspective view of another sheet stop;
- Fig. 11 is an enlarged detail perspective view of the sheet separating and forwarding devices and the supporting frame for the pack feeding mechanism;
- Fig. 12 is a detail perspective view of a pack of sheets and the sheet separating and forwarding devices, showing the latter engaged with the foremost sheet of the pack;
- Figs. 13, 14, 15, 16 and 17 are side views of the pack and the sheet separating and forwarding devices, showing the various positions occupied by the latter during operation of the same to engage, separate, and forward the sheets from the pack;
- Fig. 18 is an enlarged detail perspective view of a feed board, guide members, and a frame for the sheet conveying mechanism;
- Fig. 19 is a fragmentary sectional view of another conveyor frame;
- Fig. 20 is an enlarged fragmentary side view, partly in section, of the first named conveyor frame and associated devices, as viewed from the inner side of said frame;
- Fig. 21 is an enlarged detail perspective view of sheet pushing fingers, operating means therefor, and cams for actuating the sheet separating means;
- Fig. 22 is an enlarged detail perspective view of one of the loading mechanisms shown in Figs. 1a and 2a.
- Fig. 23 is a side elevation of a machine similar to that shown in preceding figures but equipped with another sheet separating and forwarding mechanism and another loading mechanism, embodying the present invention;
- Fig. 24 is an end view of the machine and loading mechanism shown in Fig. 23, looking from the right thereof;
- Fig. 25 is a detail perspective view of the sheet separating and forwarding mechanism shown in Fig. 23;
- Fig. 26 is a side elevation of a machine similar to those shown in preceding figures but equipped with another loading mechanism embodying the present invention;
- Fig. 27 is an end view of the machine and loading mechanism shown in Fig. 26, looking from the right thereof;
- Fig. 28 is a detail perspective view of the loading mechanism shown in Figs. 26 and 27;
- Fig. 29 is a side elevation of a machine similar to those shown in preceding figures but equipped with another loading mechanism embodying the present invention;
- Fig. 30 is an end view of the machine and loading mechanism shown in Fig. 29;
- Fig. 31 is a detail perspective view of the loading carriage shown in Figs. 26, 27, 29 and 30;
- Fig. 32 is a side elevation of a machine similar to those shown in preceding figures but equipped with another loading mechanism embodying the present invention;
- Fig. 33 is a transverse vertical sectional view on the line 33—33 of Fig. 32; and
- Fig. 34 is an enlarged side elevation of the loading mechanism illustrated in Fig. 32, showing the same in a different position.
- MACHINE FRAMEWORK AND MAIN DRIVING MECHANISM**
- Figs. 1 to 7, inclusive, 11, 18, 19, 23, 24, 26, 27, 30 and 32 to 34, inclusive*
- The machine framework is mounted on a suitable foundation 5, and includes a bed plate 6 having spaced parallel extensions 7 providing a run-way 8 for loading mechanisms or trucks to be hereinafter described. This runway 8 is provided with recesses 8' to receive the wheels of said loading mechanisms and prevent accidental displacement of the same when they are moved into operative relation with the feeder. The bed plate 6, and its extensions 7, are bolted or otherwise suitably secured to the machine foundation at 9 and 10, respectively, and said bed plate and extensions 7 have mounted thereon spaced parallel frames indicated broadly at 11 (Fig. 3). These frames 11 serve to support the movable parts of pack feeding mechanism hereinafter described, and are so placed as to enable the aforesaid loading mechanisms or trucks to be moved along the run-way 8 into and out of operative relation with said pack feeding mechanism.
- The frames 11 each have spaced parallel side members 12 which are connected together at intervals along the same by cross-members 13 secured to or formed integrally with said side members (Figs. 3 and 11). The frames 11 are of relatively low height to enable the pack feeding mechanism thereon to be conveniently loaded, and said frames and said mechanism may, if desired, be readily associated with means for conveying sheets thereabove to any desired height for delivery to another machine or instrumentality. Secured to or formed integrally with the side members 12 are front legs 14 and rear legs 15 for supporting the frames 11 in spaced parallel relation at opposite sides of the run-way 8. The front legs 14 are bolted or otherwise secured, as at 16, to the bed plate 6 and the rear legs 15 are bolted or otherwise secured at 17 to the rear portions of the extensions 7 of said bed plate. The side members 12 of the frames 11 are extended forwardly of the front legs 14, as clearly shown in Figs. 1, 2 and 11 of the drawings, and the innermost side members 12 of said frames have secured to, or formed integrally with, the forwardly extending portions thereof, brackets 18 extending at right angles from said innermost side members 12 and each provided with a series of openings 19 (Fig. 11).

Mounted between the forwardly projecting portions of the innermost side members 12 of frames 11, is a frame indicated broadly at 20 (Fig. 18). This frame 20 serves to support the 5 movable parts of sheet conveying mechanism to be hereinafter described, and said frame is comprised by side plates 21 having upwardly and forwardly curved upper edges 22 on which are secured, as at 23, anti-friction sheet supporting 10 strips 24 curved in conformity with the curved upper edges 22 of said plates 21. The ends of the strips 24 are secured by clips 25 and set screws 26, to the ends of the curved edges 22 of plates 21, and the sheet conveying mechanism 15 above referred to advances the sheets upwardly and forwardly along the strips 24 for delivery to a printing press, box forming machine or any other sheet receiving device to which it is desired to feed the sheets. The arrangement of 20 the plates 21, and the construction of the conveying mechanism thereon, is such that only one edge and opposed marginal portions of the sheets are engaged by said mechanism and said plates, respectively. This, together with the fact that 25 the strips 24 are of suitable material to prevent marring or scratching the sheets, avoids damage thereto and eliminates the possibility of the sheets being defaced in any manner.

The plates 21 may be adjusted toward and 30 away from each other to accommodate sheets of varying widths, and for this purpose said plates are connected together by telescoping stay-shafts one of which is indicated at 27, 28 in Fig. 18 of the drawings. These stay-shafts are 35 bolted or otherwise suitably secured to the side plates 21, and after the desired adjustment of said side plates has been made, the parts of stay-shaft 27, 28 are rigidly connected together by a set screw 29 carried by the hollow stay- 40 shaft part 28 and threaded therethrough into engagement with the stay-shaft part 27. The fastening bolt or device for securing the stay-shaft part 28 to one of the plates 21, is indicated at 30, and a similar bolt or device (not shown) 45 is employed for securing the stay-shaft part 27 to the other of the side plates 21. The side plates 21 have secured to, or formed integrally with, the lower forward portions thereof, lugs 31 having suitable openings therein for bolts 32 50 that pass through said openings and through certain of the openings 19 in the brackets 18 above referred to. The series of openings 19 in the brackets 18 enable the side plates 21 to be secured to said brackets by the bolts 32 in any 55 desired position of adjustment of said side plates. Secured to or formed integrally with the rear lower portions of the side plates 21, are supporting legs 33 that are suitably secured to the bed plate 6, as by machine screws 34 each of which 60 extend through one of a series of openings (not shown) formed in said bed plate transversely thereof.

Secured to, or formed integrally with, the upper forward portions of the side plates 21, 65 are forked lugs 35 which project forwardly from said side plates and are provided with apertured bosses 36. Extending loosely through the bosses 36, to rotate therein, is a shaft 37 that serves to support and brace the side plates 21. This 70 shaft 37 is journaled in suitable bearings provided by brackets 38, 39 (Figs. 1 and 2) which are bolted or otherwise suitably secured to the rear upper corners of the side frames 40, 41 that support the movable parts of the press or other 75 sheet receiving device to be fed. These side

frames 40, 41 are of the usual or any well known construction, connected together by cross-members 42, 43 and having side members 44, 45, 46, and 47, 48, 49, respectively. The side frames 40, 41 have secured to, or formed integrally therewith, supporting legs 50 that are bolted or otherwise suitably secured, as at 51, to the machine foundation 5.

Mounted on the machine foundation 5, between the side frames 40, 41, is a bed plate 52 having an extension 53 secured to or formed integrally therewith. The bed plate 52 and its extension 53 are bolted or otherwise suitably secured to the machine foundation 5, and mounted on the bed plate 52 is an electric motor 54 which is bolted or otherwise suitably secured to said bed plate at 55 (Figs. 1, 2 and 6). This motor 54 is supplied with electric current from any suitable source, by lead wires 56 (Fig. 1) which are connected with said source and said motor. The lead wires 56 run through the sections 57, 58, 59, 60 of a conduit, the section 59 constituting a housing for a switch 61 controlling the starting and stopping of the motor 54. Fixed on the armature shaft 62 of the motor 54 is a 100 pulley 63 around which passes a belt 64. This belt 64 also passes around a large pulley 65 which is fixed on a main drive shaft 66 driven from the motor 54. This shaft 66 extends transversely of the sheet conveying mechanism, and 105 is journaled in suitable bearings on the frame members 12 and 21. Fixed on the shaft 66 is a pinion 67 which meshes with a large gear 68 that is fixed on a main cam shaft 69. This cam shaft 69 also extends transversely of the sheet 110 conveying mechanism and is journaled in suitable bearings on the frame members 12 and 21. It will appear from the foregoing that the main drive shaft 66 and the main cam shaft 69 are 115 driven continuously through the described connections therefor with the motor 54.

PACK FEEDING MECHANISM

Figs. 1 to 8, inclusive, 11, 23, 26, 29 and 32

The pack feeding mechanism above referred to, is preferably operated and constructed as follows. Fixed on the cam shaft 69, at the end thereof opposite that carrying the large gear 68, is an eccentric 70 (Figs. 1 and 7) provided with an outwardly projecting eccentric pin 71. Journaled on the pin 71 is a sleeve 72 which is retained against displacement from said pin by a nut 73 threaded thereon. Secured to the sleeve 72 is one extremity of a link 74 the opposite extremity of which is secured to a block 75 that is journaled on a pin 76 carried by and projecting outwardly from, opposite sides of an arm 77 at the free end thereof. This arm 77 is loosely mounted on a shaft 78 extending transversely of the frames 11 near the forward ends thereof and journaled in suitable bearings on the side members 12 of said frames. Pivoted at 79 on the arm 77 is a pawl 80 that carries a roller 81. This pawl 80 is moved with the arm 77 by the link 74 and eccentric pin 71 so as to intermittently engage and drive a ratchet wheel 82 which is fixed on the shaft 78 (Figs. 1, 3 and 7).

Fixed on the shaft 78, and rotatable intermittently therewith, the sprockets 83 around which pass roller chains 84 that also pass around sprockets 85 fixed on the inner opposed ends of stub shafts 86. These stub shafts 86 are journaled in suitable bearings on the rear portions of the side members 12 of frames 11, and said stub shafts are spaced apart at the rear of 150

said frames and retained against endwise movement by any suitable devices for this purpose. The chains 84 extend horizontally from the front to the rear of the frames 11, and said chains, 5 together with the sprockets 83, 85 serve to support and intermittently advance a pack of sheets 87 to be separated and delivered to the press or other sheet receiving device to be fed. The pack of sheets 87 are preferably arranged to stand on edge one behind another on the upper reaches of the chains 84, and the pack rests against a plate or follower 88 which is intermittently advanced with and at the speed of the intermittently advancing chains 84. The plate or follower 88 may, if desired, be provided with anti-friction rollers 88' which prevent scratching or marring of the sheets, and said plate or follower is preferably operated, mounted, and constructed as follows.

20 Journaled on the pin 76 of lever 77 is a block 89 secured to one end of a link 90 that extends from the arm 77 rearwardly of the machine (Figs. 7 and 9). The opposite or rear extremity of the link 90 is secured to a block 91 that is pivoted on a pin 92 secured to an arm 93 at the free end thereof (Figs. 1a, 7 and 9). This arm 93 is loosely mounted on a shaft 94 which extends transversely of the frames 11 and is journaled in suitable bearings on the side members 12 thereof. Pivoted at 95 on the arm 93 is a pawl 96 carrying a roller 97. The pawl 96 is thus rocked in opposite directions with the arm 93 through the described connections therewith to the rocking arm 77. This pawl 96 is adapted, at intervals, to engage a ratchet wheel 98 that is fixed on the shaft 94, and thus impart intermittent rotation to said shaft. Fixed on the shaft 94 to rotate intermittently therewith are spur gears 99 that mesh with racks 100 secured to or formed integrally with slides 101 on the under side thereof. These slides 101 have their forward ends engaged between rollers 102 journaled on brackets 103 that are bolted or otherwise suitably secured to the outermost side members 12 of the frame 11 (Figs. 3 and 11). The slides 101 have their rear extremities engaged between rollers 104 and guides 105, the rollers 104 being journaled on brackets 106 which carry said guides and are bolted or otherwise suitably secured to the outermost side members 12 of frame 11 near the rear portions thereof (Figs. 4, 5 and 11). Said rollers and guides facilitate movement of the follower 88 and prevent tilting of the same due to the weight of the pack or supply of sheets engaged therewith.

55 Mounted on the slides 101 are brackets 107 (Fig. 7), said brackets being bolted or otherwise suitably secured, as at 108, to said slides. The brackets 107 have secured to or formed integrally therewith, vertically extending sockets 109 in which are secured the lower ends of vertical standards 110. The upper portions of the standards 110 have secured to or formed integrally therewith racks 111. Meshing with the racks 111 are pinions 112 which are fixed on, or formed integrally with, a shaft 113 that is journaled in suitable bearings provided by bosses 114 which extend vertically from brackets 115 and are secured to, or formed integrally therewith. The vertical standards 110 project through the bosses 114, and said bosses house the pinions 112 that are fixed on the shaft 113, and thus maintain said pinions in engagement with 70 the racks 111 on the standards 110. The brackets 75

ets 115 have bolted or otherwise suitably secured thereto, the follower plate 88 that engages and supports the pack of sheets 87 at the upper rear portion thereof.

It will appear, from the foregoing, that when 80 the pawls 80, 96 engage the ratchets 82, 98 to rotate the shafts 78, 94 clockwise as viewed in Fig. 7 of the drawings, the chains 84, the slides 101, the standards 110, and the follower plate 88 will move forwardly in unison to advance the pack of sheets 87 supported on said chains and resting against said plate. The rollers of the chains 84 travel on, and the upper reaches of said chains are supported by, guides 116 (Figs. 4, 5 and 11) which extend between the sprockets 83 and 85 and are bolted or otherwise suitably secured on the top of the innermost side members 12 of the frames 11. These guides 116 have secured to or formed integrally therewith guide bars 117 the grooves 118 of which are adapted to receive pack holders from the loading trucks above referred to. These pack holders will be hereinafter described in detail, and are movable from the trucks into the grooves 118 of bars 117 for connection with the chains 84 to be moved thereby along said bars. The pack of sheets 87 being advanced by the chains 84 and the follower plate 88, is engaged at opposite sides by guide bars 119, 120 for guiding the pack and maintaining it in proper position during advancing movement of the same. The guide bar 119 is of greater length than the guide bar 120 and extends to the rear of one of the frames 11 so that packs of sheets 87 loaded in the machine may be engaged with said side 100 bar to properly align the pack with various movable devices that act on the sheets thereafter. The guide bar 119 has secured thereto, or formed integrally therewith, arms 121 extending outwardly at right angles to said bar and having 105 pin and slot connections 122, 123 with one of the brackets 103 and a bracket 124 bolted or otherwise suitably secured to the outermost side member 12 of one of the frames 11. The guide bar 120 has secured to, or formed integrally therewith, an arm 125 extending outwardly at right angles to said bar and having pin and slot connections 126, 127 with another of the brackets 103 on the other outermost bar 12 of the opposite frame 11.

110 As the pack of sheets 87 is advanced by the chains 84 and the follower plate 88, the foremost sheet engages wedge-shaped blocks 128 (Fig. 7) that are bolted or otherwise suitably secured to the guide bars 117 at the top and 115 forward portions thereof. The foremost sheets of the pack are thus lifted off the chains 84 and supported by the wedge-shaped blocks 128. When the foremost sheets of the pack engage the wedge-shaped blocks 128 they also engage 120 wedge-shaped blocks 129 extending between and located in side by side relation with the wedge-shaped blocks 128. The blocks 129 are secured to or formed integrally with holders 130 (Fig. 8) that have pin and slot connections 131, 132 125 with brackets 133 secured to or formed integrally with the side plates 21 of frame 20 and projecting inwardly from said plates at right angles thereto (Fig. 18). The holders 130 and the blocks 129 carried thereby project rearwardly 130 from the brackets 133 and may be adjusted on the latter so that the wedge portions of said blocks align with the wedge portions of blocks 128 laterally of the machine. The holders 130 of the blocks 129 are retained against lateral 135

displacement by guides 134 formed on the brackets 133 and between which said holders are clamped to said brackets by the pin connections 131. Adjustably secured to the holders 130, as by pin and slot connections 135, 136 are plates 137 the rear extremities of which have secured to or formed integrally therewith vertical stops 138. The foremost sheets of the pack, when lifted and supported by the wedge blocks 128 and 129 engage the stops 138, as clearly shown in Figs. 7 and 8 of the drawings.

The front of the pack of sheets 87 is engaged at the lower corners thereof by stops 139 (Figs. 3, 8 and 11). These stops 139 extend horizontally and inwardly from vertical holders 140 to which the stops are riveted or otherwise suitably secured. The holders 140 have secured to or formed integrally therewith upwardly extending threaded shafts 141 that pass through slots 119' and 120' of guide bars 119 and 120. Threaded on the shafts 141 at opposite sides of bars 119 and 120, are adjusting and locking nuts 142, 143 which secure the holders 140 on said bars and enable said holders and the stops 139 to be adjusted vertically to any desired position. The stops 139 and their holders 140 are adjustable laterally of the machine to various positions, through movement of the threaded shafts 141 of said holders along the slots 119' and 120'.

When the front of the pack of sheets 87 engages the stops 138 and 139, it also engages stops 144 that bear against the front of the pack at the upper corners thereof (Fig. 8). These stops 144 are pivoted at 145 on holders 146 and extend horizontally and inwardly toward each other from said holders. The holders 146 are mounted for lateral adjustment toward and away from each other in apertured bosses 147 of sleeves 148 that are slidably mounted on vertical standards 149 anchored at their lower ends in sockets 150 secured to or formed integrally with the outermost side members 12 of frames 11. The stops 144 are secured in the bosses 147 by set screws 147' that enable said stops to be adjusted laterally of the machine, as desired, in order to accommodate sheets of various widths. The stops 144 yieldably engage the front of the pack of sheets 87 through the action of spring pressed rods 151 the rear ends of which are pivotally connected with said stops at 152. The forward ends of the rods 151 are guided in suitable openings in forwardly and inwardly extending brackets 153 that are secured to or formed integrally with the holders 146. The springs 154 for the rods 151 are retained thereon between the forward ends of brackets 153, and collars 155 secured to said rods by set screws 156. Accidental displacement of the rods 151 from the brackets 153 is prevented by collars 157 which are secured on the rods forwardly of the brackets by set screws 158. When the supply or pack of sheets is engaged with the stops 138, 139, 144, the front portion of said supply or pack is elevated by the wedge-shaped blocks 128, 129, as previously described.

The stops 144 are adjustable vertically in accordance with sheets of various heights to be handled in the machine. Vertical adjustment of the stops 144 is preferably obtained through the medium of the following devices. Journaled in suitable bearings 159 on the sleeves 148, is a shaft 160 having secured to, or formed integrally with the opposite ends thereof, pinions 161 which engage racks 162 that are secured to or

formed integrally with the standards 149 at the upper ends thereof. Fixed on the shaft 160, at one end thereof, is a hand wheel 163 which, when rotated, rotates the shaft 160 and pinions 161 and thereby causes the sleeves 148 and the stops 144 to move up or down on the standard 149 in accordance with the direction of rotation of the hand wheel 163. The sleeves 148 cooperate with scales 164 on the standards 149 whereby the stops 144 may be set at various heights of sheets indicated by said scales. The stops 144 are preferably constructed of sheet metal, and have bent inner opposed ends which engage the front of the pack of sheets 87 at the upper corners thereof. The sheet stops 144 may, however, be replaced by sheet stops of the type indicated in Fig. 10 of the drawings, and each having a roller 165 journaled on the inner end of the sheet stop 166 and adapted to engage the adjacent upper corner of the pack of sheets at the front thereof. The construction of each sheet stop 166 is otherwise the same as the construction of the sheet stops 144, and each sheet stop 166 is mounted and operated in exactly the same manner as the sheet stops 144.

CONTROL MEANS FOR THE PACK FEEDING MECHANISM

Figs. 1, 2, 6, 7 to 10, inclusive, 23, 26, 29 and 32

105

The intermittent advancing movement of the pack of sheets 87 by the described mechanism for this purpose, is controlled automatically as the sheets are separated successively from the front of the pack by sheet separating and forwarding devices to be hereinafter described. This automatic control of the advancing movement of the pack of sheets 87 is preferably obtained through mechanism operated and constructed as follows. Fixed on the continuously rotating cam shaft 69, adjacent one end thereof, is a cam 167 (Figs. 6 and 8). This cam 167 is adapted to engage a roller 168 journaled on the forward ends of a lever 169 that is pivoted at 169' on one of the side members 12 of one of the frames 11. Secured to the lever 169 is one extremity of a spring 170 the opposite or upper extremity of which is secured to a threaded adjusting bolt 171 extending upwardly through, and threaded in, an opening formed in the forward part of an arm 172 (Fig. 1). This arm 172 is formed integrally with the boss 147 of one of the sleeves 148. The adjusting bolt 171 is secured in any desired position of adjustment on the arm 172, by a lock nut 173, which is threaded on said bolt at the under side of said arm. Through the described connections for the spring 170 with the arm 172, the tension of said spring may be regulated as described, while at the same time said connections provide for raising or lowering movement of the arm 172 with the stop holder 146 on which it is carried.

110

Pivoted connected, as at 176, with the arm 169 at the end thereof opposite that carrying the roller 168, is one end of a bent link 177, the opposite or upper end of which extends through a sleeve 178 and is secured thereto by a set screw 179. This sleeve 178 is pivotally connected at 180 with the free end of an arm 181 that is fixed on a shaft 182 at one end thereof. The shaft 145 182 is journaled in suitable bearings 183 on the sleeves 148 that carry the stops 144 and the shaft 160, the sleeve 178 and the set screw 179 providing for adjustment of the shaft 182 vertically with the sleeves 148 and enabling the link 177 150

185

190

to be connected with the arm 181 in any position of vertical adjustment of said sleeves. Fixed on the shaft 182, as by set screws 184, are holders 185 for rods 186 that have downwardly bent 5 detector fingers 187 movable into and out of engagement with the front of the pack of sheets 87 adjacent the forward upper edge thereof. Prior to separation of the foremost sheet of the pack by the sheet separating and forwarding 10 mechanism, the detector fingers 187 are lifted by the cam 167 so that said fingers move exteriorly of the pack across a margin thereof and are disengaged from the sheet. The foremost sheet is then separated from the front of 15 the pack, whereupon the detector fingers 187 are lowered by the springs 170 so that said fingers move interiorly across said margin and engage the next sheet at the front of the pack, as before described. The rods 186 are secured in the holders 185 by set screws 188 that enable the detector fingers 187 to be adjusted and set in proper position for engagement with the front of the pack of sheets 87. The raising and lowering movement of the detector fingers 187 occurs 20 once during each cycle of operation of the machine whether the pack of sheets 87 is at rest or whether said pack is being advanced after a predetermined number of sheets have been successively separated from the front thereof. It is 25 important to note, however, that when the pack of sheets 87 is at rest, and tightly pressed against the stops 138, 139, and 144, the front of said pack is advanced sufficiently to prevent the fingers 187 from lowering so that the roller 168 30 will be pulled by the spring 170 into engagement with the low part of the cam 167. It will thus appear, that with the pack of sheets 87 at rest as before described, the roller 168 will be engaged by the high part of the cam 167 to lift 35 the fingers 187, but that the foremost sheets of the pack will prevent said fingers from lowering a distance sufficient to enable the spring 170 to pull the roller 168 into engagement with the low part of the cam 167 and thus rock the shaft 40 through an appreciable arc. When a sufficient number of sheets have been removed successively from the front of the pack, however, the fingers 187 are lowered so that the spring 170 rocks the arm 169 and the shaft through 45 arcs great enough to enable the roller 168 to engage both the low and high parts of the cam 167 and to enable the shaft 182 to operate devices controlling the movement of the pack advancing means. These devices are preferably 50 constructed and operated as follows.

Fixed on the shaft 182 at the end thereof opposite that carrying the arm 181 is an arm 189 (Fig. 8). Pivotedly connected at 190 with the arm 189 at the free end thereof, is a sleeve 189' 55 in which is secured one extremity of a link 191 that extends downwardly through a sleeve 192 and is secured thereto by a set screw 193. This sleeve 192 is pivoted at 194 on one end of a lever 195 which, in turn, is pivoted at 196 on one of the standards 149. The opposite end of the lever 195 has a pin and slot connection 197, 198 with the upper end of a link 199. The lower end of the link 199 is pivotedly connected at 200 with a pawl 201 that is pivoted at 202 on the bracket 150 for the standard 149 that carries lever 195.

The pawl 201 is adapted to be engaged with, and disengaged from, a notch 203 formed in a block 204. This block 204 is secured at 205 on 75 a link 206 one end of which is pivotedly con-

nected at 207 with a cam or pawl masking element 208 that is loosely mounted on the shaft 78 (Fig. 9). The opposite end of the link 206 is pivotedly connected at 209 with the upper end of a lever 210 which, in turn, is pivoted at 211 on a side member 12 of one of the frames 11. The lever 210 also has pivotedly connected therewith, at 209, one end of a link 212 the opposite end of which is pivotedly connected at 213 with a cam or pawl masking element 214 that is pivotedly mounted on the shaft 94. Pivoted at 215 to the lower end of the lever 210 is one extremity of a link 216 the opposite extremity of which is pivotedly connected at 217 with the free end of an arm 218. This arm 218 is pivoted at 219 on a side member 12 of one of the frames 11, and said arm has journaled thereon a roller 220 which is adapted to be engaged by a cam 221 that is fixed on the cam shaft 69. Pivotedly connected at 222 with the arm 218 is one end of a spring pressed rod 223 the opposite end of which extends loosely through a suitable opening formed in a bracket 224. This bracket 224 is bolted or otherwise suitably secured to a side member 12 of one of the frames 11, and said bracket forms an abutment for one end of a spring 225 mounted on the rod 223. The opposite end of the spring 225 bears against a collar 226 secured on the rod 223 between the opposite ends thereof.

When the sheets 87 are at rest, the cams or pawl masking element 208 and 214 engage the rollers 81, 97 of pawls 80, 96, and prevent said pawls from engaging the ratchets 82, 98 as the arms 77, 93 are rocked by the described connections therefor with the crank pin 71 of the continuously rotating eccentric 70. While the pawls 80, 96 are thus prevented from engaging the ratchets 82, 98, the pawl 201 is engaged in the notch 203 of block 204. At this time, slight motion is imparted to the block 204 and the cams 208, 214 by the described connections therefor with the arm 218. The arm 218, in turn, has a slight rocking motion imparted thereto by the spring 225, and engagement of the high part of the cam 221 with the roller 220. The spring 225, however, is prevented from swinging the arm 218 forwardly through any appreciable distance, by engagement of the pawl 201 with the block 204. The block 204 has an upwardly and rearwardly inclined portion 227 (Fig. 8) that enables said block to move forwardly while the pawl 201 is engaged therewith. The pawl 201 thus has a slight vertical motion which is imparted to the link 199, this slight vertical motion of the link 199 being accommodated by the pin and slot connection 197, 198 for said link with the lever 195. At this time the lever 195 also has a slight rocking motion imparted thereto by the shaft 182. This slight rocking motion of the lever 195, however, is insufficient to lift the link 199, and the pawl 201 therefor remains engaged with the block 204.

As the sheets are separated successively from the front of the pack, however, the amount of lowering movement of the detector fingers 187 successively increases so that finally the arm 195 is rocked by the shaft 182 a sufficient distance to impart a rocking movement of greater extent to the lever 195. The lever 195 then lifts the link 199, whereupon the pawl 201 is disengaged from the block 204 and the spring 225 swings the lower ends of the levers 210 and 218 forwardly until the roller 220 engages and follows the low part of the cam 221. The lever 150

218 thus receives its maximum forward motion, whereupon the cams 208, 214 are rocked rearwardly out of engagement with the rollers 81, 97 of pawls 80, 96. Thereupon said pawls, when 5 rocked forwardly with the arms 77, engage the ratchet wheels 82 and 98, respectively, thus rotating shafts 78 and 94 clockwise as viewed in Figs. 7 and 9 of the drawings, so that the chains 84, the slides 101, and the follower plate 88 are 10 moved forward by the driving connections therefor with said shaft. The pack of sheets 87 is thus advanced one or more steps forwardly, during which time, the arm 218 has maximum swinging movement imparted thereto by the 15 cam 221 and the spring 225. This movement, in turn, is imparted to the cams 208, 214 by the described connections therefor with the arms 218.

As the pack of sheets advances, the amount 20 of lowering movement of the detector fingers 187 successively decreases, until finally the shaft 182 and the lever 195 are not rocked sufficiently to enable the latter to lift the link 199 and the pawl 201. Thereupon the pawl 201, on forward 25 movement of the block 204 and the cams 208, 214, engages said block so that rearward movement of said cams is prevented. The cams 208, 214 thus engage the rollers 81, 97 of pawls 80, 96 and prevent the latter from engaging 30 the ratchet wheels 87, 98. Movement of the pack advancing means is thus prevented until further sheets have been separated successively from the front of the pack, whereupon the pack is again advanced and stopped, as previously 35 described. These operations are repeated in sequence to advance the pack of sheets 87, and further description of the pack advancing and controlling mechanism is therefore not necessary. It may be mentioned, however, that in 40 order to prevent the pack and its supporting and advancing mechanism from being accidentally moved rearwardly of the machine, particularly when the sheet separators are moved into engagement with the front sheet of the 45 pack, a side member 12 of one of the frames 11 has pivoted thereon at 228 and 229 pawls 230 and 231, respectively. The pawl 230 is maintained in engagement with the ratchet wheel 82 by a spring 232, the opposite ends of 50 which are connected to said pawl and the bracket 224, respectively. The pawl 231 is maintained in engagement with the ratchet wheel 98 by a spring 233, the opposite ends of which are connected with said pawl and a bracket 234, respectively. This bracket 234 is bolted or otherwise suitably secured to a side member 12 of one of the frames 11. The pawls 230 and 231 prevent rotation of the ratchet wheels 82, 98 55 in a counterclockwise direction, as viewed in Fig. 9 of the drawings, and thus prevent the pack supporting and advancing mechanism and the pack from being moved rearwardly of the machine when the sheet separators are moved into engagement with the front sheet of the pack. 60 When it is desired to move said pack supporting and advancing mechanism rearwardly of the machine, for reloading or any other purpose, the pawls 80, 230 and 96, 231 may be disengaged 65 from the ratchet wheels 82, 98, whereupon the follower plate 88 and the chains 84, comprising the pack advancing mechanism, may be moved rearwardly of the machine. Lifters 509', 509" for the pawls 90 and 80 are mounted on the arms 93 and 77 for movement inwardly and outwardly 70 75 to lift said pawls and enable them to engage the

ratchets 98, and 82, respectively. It will, of course, be understood from the foregoing that rearward movement of the chains 84 may be produced independently of the plate 88, and vice versa and, in order to move the chains 84 manually in either direction, the shaft 78 is provided with a hand wheel 78'.

SHEET SEPARATING AND FORWARDING MECHANISM

Figs. 1, 2, 6, 7, 11 to 17, inclusive, 21, 23, 25, 26, 29 and 32 85

The sheet separating and forwarding mechanism comprises lower suction devices 235 spaced apart transversely of the machine, and upper suction devices 236, likewise spaced apart transversely of the machine and cooperating with said lower suction devices to separate the sheets 87 successively from the front of the pack 87 and forward them in like manner to the sheet conveying mechanism. The lower and upper suction devices 235, 236 are adjustable vertically and transversely of the machine, in accordance with various sizes of sheets handled therein, and are supported on and operated by devices to be hereinafter described. The devices for operating the upper and lower suction devices are constructed, actuated, and timed so as to impart the following movements to said upper and lower suction devices during each cycle of operation of the machine. The suction devices 235, 236 are rocked upwardly and rearwardly to engage the foremost sheet of the pack at points aligned vertically between the stops 138, 139, the lower suction devices 235 being moved into engagement with said sheet before the upper suction devices are moved into engagement therewith, and said lower suction devices having suction created therein after they have engaged the sheet. This is illustrated diagrammatically in Fig. 13 of the drawings, where-in it will be noted that the lower suction devices 235 have engaged the foremost sheet of the pack above and between the stops 138, 139 and the suction devices 236 are moving toward said pack to engage said foremost sheet after it is 100 engaged by the suction devices 235.

Just before the upper suction devices 236 engage the foremost sheet of the pack, suction is created in said devices whereupon they engage 105 said sheet with a rearward holding or pressing action, the lower suction devices 235 at this time moving upwardly and forwardly to buckle the sheet as shown in full lines in Figs. 12 and 14 of the drawings. The upper suction devices 236 then begin to move away from the pack with 110 the lower suction devices 235 and said upper and lower suction devices disengage the lower edge of the foremost sheet of the pack from stops 138 and buckle said sheet as shown in dotted lines in Fig. 12 and full lines in Fig. 15, of the drawings. Because of the formation and setting of the separator actuating cams hereinafter referred to, and the difference in diameters of the circles through arcs of which the upper and lower suction devices travel, the upper suction 115 devices are able to overcome their delayed start forwardly of the pack and thus catch up with the lower suction devices. It will therefore be apparent that during part of the cycle of operation of the upper and lower suction devices, they have a differential movement which results in the production of one or more buckles extending in one direction, followed by the production of another buckle extending in a direction angularly related to, or transversely of, 120

80

90

150

said first named direction, the successive formation of buckles in this manner insuring separation of the sheets from the pack regardless of the character of the material or the amount 5 of adhesion between the sheets of the pack.

After the upper suction devices have caught up with the lower suction devices, and the two move away from the pack to buckle the sheet in angularly related directions, as stated, said 10 upper and lower suction devices continue to move away from the pack and further buckle or flex the sheet as shown in Fig. 16 of the drawings. The upper and lower suction devices then continue to move away from the pack 15 and disengage the sheet from stops 139, 144 whereupon the sheet straightens out as shown in Fig. 17 of the drawings, prior to delivery of said sheet by said suction devices to the conveyor 238. When the sheet is separated and 20 advanced from the pack by the suction devices 235, 236, as described, said sheet is carried so that the top of the sheet travels forwardly and downwardly and the lower edge of the sheet travels forwardly and upwardly, from the position 25 shown in Fig. 17 of the drawings. The separated sheet is then delivered by the suction devices 235, 236 against the strips 24, whereupon the lower edge of the sheet is engaged by hooks 237 on the chains 238 of the sheet conveying mechanism and suction is immediately 30 broken in said suction devices. At this time, the upper suction devices 236 are rocked outwardly beyond the lateral marginal edges of the sheet and the lower suction devices are 35 rocked within the arc of strips 24, to enable the hooks 237 to push the sheet, without interference, upwardly and forwardly over said strips 24 and the side plates 21 for delivery to the press or other sheet receiving device to be fed.

After the lower and upper suction devices 235, 236 are rocked downwardly and forwardly to their lowermost positions, and the sheet has passed upwardly and forwardly along the strips 24 beyond the path of travel of the upper suction devices 236, the latter are rocked upwardly and rearwardly with the lower suction devices 235. As the upper suction devices 236 are rocked upwardly and rearwardly, they are also rocked inwardly of the lateral edges of the 50 next sheet and act in conjunction with the suction devices 235 to engage said sheet and separate and advance it from the pack as in the case of the preceding sheet. These operations are repeated in a substantially continuous manner to successively separate the sheets from the pack and forward them to the sheet conveying mechanism for delivery thereby to the printing press or other sheet receiving device to be fed. It will, of course, be understood, that the feeder 55 including the suction devices 235, 236 may be associated with horizontally extending sheet conveying means of any suitable style, and that said feeder may, in this case, be operated so that the suction devices 235, 236 carry the sheets forwardly and drop them onto said conveyor. If, while the sheet separating devices 235, 236 are separating a sheet from the supply, additional sheets or a portion of the supply should, for any reason be advanced past the 60 stops at the front of the supply, said devices will, on their return push such additional sheets or portion of the supply rearwardly to said supply for separation of the next sheet as before described.

The lower suction devices 235 above referred

to, are preferably operated and constructed as follows. Secured to or formed integrally with the outermost side member 12 of one of the frames 11, is a bracket 239 (Figs. 2a and 7) through an apertured boss of which projects 80 one extremity of a spring pressed rod 240. The spring 241 for this rod is mounted thereon forwardly of the bracket 239 and retained between the latter and a collar 242 adjustably secured on said rod (Figs. 2 and 7). The forward end 85 of the rod 240, is pivotally connected at 243 with the free end of an arm 244 that is fixed on a rocking sleeve 245. This sleeve 245 is rotatably mounted on a rod 245' and extends there- with transversely of the machine through suitable openings in the frames 11. Endwise displacement of the rod and sleeve in frames 11, is prevented by any suitable means for this purpose, and said rod and sleeve extend through 90 openings of forked arms 246 secured to or 95 formed integrally with the side plates 21 of frame 20 at the rear lower corners thereof (Figs. 2 and 18). Fixed on the sleeve 245, and projecting downwardly and forwardly thereof is an arm 247 (Figs. 2 and 7 and 21) on the free end of 100 which is journaled a roller 248 that engages a cam 249 fixed on the continuously rotating cam shaft 69. It will thus appear that the sleeve 245 is rocked continuously by the spring pressed rod 240 and the cam operated arm 247.

Fixed on the sleeve 245 are holders 250 in which are anchored the lower ends of rods 251 (Figs. 7 and 11). Adjustably mounted on the upper ends of the rods 251, and secured thereto as by set screws 252, are brackets 253 in which 110 are mounted eye-bolts 254. These eye-bolts 254 are secured in any desired angular position on the brackets 253, by lock nuts 255. Extending loosely through the eyes of bolts 254 are threaded tubes 256 on which are mounted the lower 115 suction devices 235. Mounted on the tubes 256 between the eye-bolts 254 and the suction devices 235 are springs 257 that provide for yielding movement of the suction devices 235 when they engage the foremost sheet of the pack. 120 The tubes 256 are retained against displacement from eye-bolts 254 by adjusting nuts 258 threaded on the tubes 256 at the ends thereof opposite those carrying the suction members 235. Suction is made and broken in the threaded 125 tubes 256 and the suction members 235 at regular intervals by means for this purpose to be hereinafter described, and it will appear from the foregoing, that when the sleeve 245 is rocked by the described means for this purpose, the rods 130 251 and the suction devices 235 carried thereby, will also be rocked to move said devices upwardly and rearwardly into engagement with the foremost sheet of the pack, and then forwardly and downwardly to separate said sheet and advance it from the pack in conjunction with the upper suction devices 236.

The upper suction devices 236, above referred to, are preferably operated and constructed as follows. Secured to or formed integrally with 140 the outermost side member 12 of one of the frames 11 is a bracket 259 (Fig. 2a) through an opening of which projects the rear end of a spring pressed rod 260. The spring 261 for this rod is mounted thereon between the bracket 259 145 and a collar 262 (Fig. 2) adjustably mounted on said rod and secured thereto in any suitable manner. The forward end of the spring pressed rod 260 is pivotally connected at 263 with the free end of an arm 264 that is fixed on a rock- 150

- shaft 265. This rockshaft 265 extends transversely of the machine and is journaled in suitable bearings on the forwardly projecting portions of the side members 12 of frames 11, and 5 on the side plates 21 of frames 20. The rockshaft 265 has fixed thereon an arm 265^a (Figs. 1, 2, 6 and 25) provided at its free end with a roller 265^b which engages a cam 265^c that is fixed on the cam shaft 69 and acts, in conjunction with the spring-pressed rod 260, to rock the shaft 265. Fixed on the rockshaft 265 are arms 266 having pin and slot and connections 267, 268 with the forward ends of links 269 (Figs. 6 and 11). The rear ends of the links 10 269 are pivotally connected at 270 with brackets 271 that are adjustably mounted on the upper ends of rods 272 and secured thereto by set screws 273. The lower ends of the rods 272 are anchored in holders 274 that are loosely mounted 15 on the sleeve 245 and retained against endwise displacement thereon by collars 275 secured in any suitable manner to said sleeve at opposite sides of the holder 274.
- Secured to or formed integrally with the 20 brackets 271 are tubular sockets 276 through which extend rods 277. The rods 277 are provided with pins 278 which extend through slots 279 formed in the walls of the tubular sockets 276. The rods 277 are rotatable in the sockets 276, the amount of rotation of said rods being limited by engagement of the pins 278 with the opposite ends of the slots 279. In addition to this function of the pins 278, said pins also serve to prevent displacement of the rods 277 from 25 the sockets 276. Mounted on the rods 277 are coil springs 280 corresponding ends of which are secured to the sockets 276. The opposite ends of the coil springs 280 are connected with arms 281 that are rigidly secured to the rods 277 by set screws 282. These arms 281 have journaled on the free ends thereof, rollers 283 maintained in engagement with cam rails 284 by the springs 280. These cam rails 284 are bolted or otherwise suitably secured to the side members 30 35 40 45 50 55 60 65 70 75
- 21 of frame 20 and project upwardly and rearwardly on said side members toward the front of the pack of sheets supported by the chains 84 and the follower plate 88. Adjustably mounted on the rods 277 adjacent the arms 281, and secured to said rods, as by set screws 285, are brackets 286 provided with openings in which are mounted eye bolts 287. These eye bolts may be adjusted to various angular positions on the brackets 286, and are secured against displacement therefrom by lock nuts 288. Extending loosely through the eyes of the bolts 287 are threaded tubes 289 on the rear ends of which are mounted the upper suction devices 236. Mounted on the threaded tubes 289 between the suction devices 236 and the eye bolts 287, are coil springs 290 that provide for yielding movement of the suction devices 236 when they engage the front of the pack of sheets 87. Displacement of the threaded tubes 289 from the eye bolts 287 is prevented by adjusting nuts 291 that are threaded on said tubes forwardly of the brackets 287. Suction is created and broken in the threaded tubes 289 and the suction members 236 by the devices for this purpose to be hereinafter described.
- The rods 272 and the parts carried thereby including the upper suction devices 236, are rocked upwardly and rearwardly and forwardly and downwardly in unison with the lower suction devices 235, by the shaft 265 and the described
- connections therefor with said rods. Rocking movement of the upper suction devices 236 longitudinally of the machine, is accompanied by rocking movement of said suction devices laterally of the machine, this lateral rocking movement of the suction devices 236 being effected by the springs 280 on the rods 277 and the cams 284 which engage the rollers 283 of the arms 281. When the suction devices 235, 236 are rocked upwardly and rearwardly to engage the foremost sheet of the pack, the rollers 283 engage the high part of the cam rails 284 and thus swing the suction devices 236 toward each other inwardly of the lateral margins of the foremost sheet of the pack. This inward swinging movement of the suction devices 236 compresses the springs 280, and when said suction devices move forwardly and downwardly with the suction devices 235, and the sheet separated and advanced from the stock by said devices is engaged by the hooks 237 on the chains 238 of the sheet conveying mechanism, the rollers 283 engage the low parts of the cam rails 284, and the springs 280 swing the arms 281 inwardly toward each other and rotate the rods 277 so that the suction members 236 are swung outwardly beyond the lateral marginal edges of the sheet as before described.
- In the embodiments of the invention shown in Figs. 23 to 34, inclusive, the upper and lower sheet separating and forwarding devices 235 and 236 have the same construction and operation as previously described except that the means for rocking the upper suction devices 236 laterally are dispensed with and said devices are mounted on rods 272' of greater length than the rods 272. These rods 272' are secured on the rock shaft 245' and, with the upper suction devices 236, are swung upwardly and rearwardly and forwardly and downwardly by the shaft 265 and the connections 266, 269, 271 therefor with said rods. The cam 265^c in this case, is set or formed in a manner such that the upper suction devices 236, as well as the lower suction devices 235, pass forwardly and downwardly within the arcs of the curved sheet supporting strips 24 and thus enable the hooks 237 to move the sheets, without interference, along said strips.
- SUCTION AND CONTROL MEANS FOR THE SHEET SEPARATING AND FORWARDING DEVICES 125
- Figs. 1, 2, 6, 11, 23, 26, 29, and 32*
- The suction and control means for the suction sheet separating and forwarding devices are preferably operated and constructed as follows. Fixed on the armature shaft 62 of the motor 54 is a sprocket 292 around which passes a chain 293. This chain 293 also passes around a sprocket 294 that is fixed on the shaft 295 of a rotary suction pump 296. The suction pump 296 is bolted or otherwise suitably secured, as at 297, on the extension 53 of the bed plate 52 that carries the motor 54. This suction pump 296 may be of the usual or any well known form used in association with sheet separating and forwarding mechanism and requiring no detailed description as respects the pump construction. The suction pump 296 may, however, be provided with an exhaust manifold 298, a relief valve 299, and a nipple 300 for connection of the sheet separating and forwarding devices with the suction side of the pump.
- Connected with the nipple 300 is a main suc- 150

tion conduit 301 of flexible material and having a normally open rotary valve 302 therein. The stem of this valve 302 has fixed thereon an arm 303 with which is pivotally connected one end of a link 304. The opposite end of the link 304 is connected with mechanism (not shown) for controlling the suction in the sheet separating devices in the event a sheet is absent at, or improperly delivered to the press or other sheet receiving instrumentality to be fed. The mechanism just referred to, forms no part of the present invention and it is therefore unnecessary to describe or illustrate the same. The suction conduit 301 is connected at 305 with the tubular arm 306 of a T-union, the head of which is formed by tubular extensions 307 and 308. The tubular extension 307 has connected therewith one end of a flexible conduit 309 the opposite end of which is connected with a pipe 310 at a point intermediate the opposite ends thereof. Connected with the opposite ends of the pipe 310 are the lower ends of vertical pipes 311 which are secured in any suitable manner to the side plates 21 of the frame 20 on the forward outer portions thereof. The upper ends of the pipes 311 have connected therewith corresponding extremities of flexible conduits 312 the opposite extremities of which are connected with the threaded tubes 256 of the lower suction sheet separating and forwarding device 235.

The extension 308 of the above mentioned T-union, has connected therewith one end of a flexible conduit 313 the opposite end of which is connected with a horizontally extending pipe 314 at a point intermediate the opposite ends thereof. Connected with said opposite ends of the pipe 314 are the lower ends of vertical pipes 315 that are secured in any suitable manner to the frames 40, 41 at the rear thereof. The upper ends of the pipes 315 have connected therewith corresponding extremities of flexible conduits 316 the opposite extremities of which are connected with the threaded tubes 289 of the upper sheet separating and forwarding devices 236. It will thus appear that the pump 296, through the described connections therefor with the lower and upper sheet separating and forwarding devices 235, 236, creates suction in said devices enabling them to grip and separate the sheets 87 successively from the pack thereof supported by the chains 84 and the plate 88. The suction in the devices 235, 236 and in the described system connecting them with the pump 296, is made and broken at regular intervals, suction being created in the suction devices 235, 236 when they engage the foremost sheet of the pack 87, and being broken after said sheet has been separated from the pack and forwarded therefrom by said devices to the sheet conveying mechanism. Making and breaking of the suction in the suction devices and said system, as stated, is preferably effected by a master valve and auxiliary valves, and these valves are preferably operated and constructed as follows.

Secured to the outermost side member 12 of one of the frames 11, and projecting outwardly therefrom, is a pin 317 (Fig. 6) having an opening through which projects the rear end of a spring pressed rod 318. The spring 319 for this rod is mounted thereon forwardly of the pin 317, one end of said spring bearing against said pin, and the opposite end of the spring bearing against a collar 320 adjustably mounted on the

rod 318 and secured thereto in any suitable manner. The forward end of the rod 318 is pivotally connected at 321 with an arm 322. This arm 322 is pivotally mounted on a pin 323 secured to the side frame member 12 that carries the pin 317. The arm 322 depends from the pin 323, and journaled on said arm intermediate its opposite ends and below the pivotal point 321, is a roller 324 that engages a cam 325. This cam 325 is fixed on the end of the cam shaft 69 opposite that carrying the eccentric 70 which operates the pack feeding mechanism.

The lower end of the arm 322 has pivotally connected therewith, at 326, one extremity of a link 327 the opposite extremity of which is pivotally connected at 328 with an arm 329. This arm 329 is fixed on a rotary valve 330 the casing 331 of which is attached to the above mentioned T-union and communicates with the tubular arm 306 thereof. The valve casing 331 is arranged between, and secured to spaced arms 332 of a bracket 333 which is bolted or otherwise suitably secured to the side member 12 that carries the pins 317 and 323. The valve 330 also has fixed thereon, and formed integrally with the arm 329, a handle 334 by which said valve may be manually opened and closed, if desired. In the normal operation of the apparatus, however, the valve 330 is opened and closed by the link 327 which has reciprocating motion imparted thereto for this purpose by the cam and spring operated arm 322. The casing 331 for the valve 330 is open at the top thereof, and when said valve is open, the pump 296 is in communication with the atmosphere and suction is broken in the sheet separating and forwarding devices 235, 236 and described connections therefor with said pump. When the valve 330 is closed, the pump 296 creates suction in the sheet separating and forwarding devices 235, 236 and the system comprised by the described conduits connecting said devices with said pump. It will thus appear that when the valve 330 is operated automatically, as described, suction will be made and broken at regular intervals in the conduits which connect the valve casing 331 with the devices 235, 236. The valve 330 constitutes the main control means for the separating and forwarding devices 235, 236.

This making and breaking of suction at intervals in said conduits is supplemented by auxiliary valves that enable the suction to be made in the lower devices 235 and the upper devices 236, successively, and to be broken in said lower devices and said upper devices, successively. These auxiliary valves are preferably operated and constructed as follows. Fixed on the continuously rotating cam shaft 69, between the eccentric 70 and the outermost side member 12 of one of the frames 11, is a cam 334 that engages a roller 335 (Figs. 1, 7 and 9). This roller 335 is journaled on one arm 336 of a bell crank 337 that is rotatably mounted on a rock shaft 338 extending transversely of the machine and journaled in suitable bearings on the side members 12 of the frames 11 and the side plates 21 of the frame 20. The other arm 339 of the bell crank 337 has connected therewith one end of a spring 340 the opposite end of which is connected with the last mentioned outermost side member 12 at the forward end thereof. The lower end of the bell crank arm 339 has pivotally connected therewith at 341, one extremity of

SHEET CONVEYING MECHANISM

Figs. 1, 2, 6, 17 to 19 inclusive, 20, 23, 26, 29,
and 32

a link 342 the opposite extremity of which is pivotally connected with an arm 343 (Fig. 1). This arm 343 is fixed on a rotary valve 344 the casing 345 of which is open at the top and connected with an extension 346 of the pipe 310 (Fig. 6). The valve 344 is thus opened and closed by the link 342 which for this purpose has reciprocating motion imparted thereto by the cam and spring operated bell crank 337. 10 When the valve 344 is open, suction in the conduits 310, 311, 312 and the devices 235 is broken, and when the valve 344 and the valve 330 are closed suction is created in said conduits and said devices.

15 Fixed on the continuously rotating cam shaft 69 between the cam 221 and the outermost side member 12 of one of the frames 11, is a cam 347 that engages a roller 348 (Figs. 6 and 7). This roller 348 is journaled on one arm 349 of a bell crank 350 that is loosely mounted on the shaft 338 to rock thereon. The other arm 351 of the bell crank 350 has connected therewith one extremity of a spring 352 the opposite extremity of which is connected with a side member 12 of one of the frames 11. The free, lower end of the arm 351 has pivotally connected therewith at 353, one extremity of a bent link 354 the opposite extremity of which is pivotally connected at 355 with an arm 356 (Fig. 6). This arm 356 is fixed on a rotary valve 357 the casing 358 of which is open at the top and mounted on an extension 359 of the pipes 314 and 315 in communication therewith. It will thus appear that the valve 357 is opened and closed by the link 354 which for this purpose has reciprocating motion imparted thereto by the spring and cam operated bell crank 350. When the valve 357 is open, suction is broken in the conduits 315, 316 and the upper devices 236, and when the valve 357 and the valve 330 are closed, suction is created in said conduits and said upper devices. The valves 344 and 357 constitute the auxiliary control means for the sheet separating and forwarding devices 235, 236.

40 The cams 325, 334 and 347 are fixed on the cam shaft 69 in such angular relation, and are of such configuration, that the valves 330, 344 and 357 are closed successively in the order named. Due to the setting of said cams, and the configuration thereof, the valves 344, 357 and 330 are successively opened in the order named, the valve 330 opening last to break any suction existing in the pipes 310, 314, and closing first to create suction in said pipes before the valves 344 and 357 are successively closed. From the foregoing it will obviously appear that as the lower and upper suction devices 235, 236 successively engage the foremost sheet of the pack, suction is successively created in said devices, and that when the lower and upper suction devices 235, 236 separate the sheet from the pack and forward it to the sheet conveying mechanism, the suction in the devices 235, 236 is broken successively, as before stated. Breaking of suction in the lower suction devices 235 occurs at the instant the lower edge of the sheet is engaged by the hooks 237 of chains 238 of the sheet conveying mechanism, whereupon suction is immediately broken in the upper suction devices 236 and the latter are moved outwardly beyond the lateral edges of the sheet to enable it to rest on the curved anti-friction strips 24 and be moved without interference, upwardly and forwardly thereon by the sheet conveying mechanism which will now be described in detail.

80 The sheet conveying mechanism is preferably operated and constructed as follows. Fixed on the main drive shaft 66, to rotate continuously therewith, is a sprocket 360 around which passes a continuously driven chain 361 (Fig. 6). This chain 361 also passes around a sprocket 362 that is fixed on, and continuously drives, the shaft 37. Fixed on the shaft 37, between the forked lugs 35 of side plates 21, are sprockets 363 around which pass the chains 238. These chains are each provided at corresponding points thereon with sets of the hooks 237 that successively engage the sheets at the lower edges thereof as they are successively separated and advanced from the front of the pack by the sheet separating and forwarding mechanism. The chains 238 are guided upwardly and forwardly on guides 364 secured to or formed integrally with the curved upper edges 22 of the side plates 21, and curved in conformity with said edges and the sheet supporting strips 24. The chains 238 also pass 90 around sprockets 365 and 366. The sprockets 365 are idlers journaled loosely on the sleeve 245 between the arms of the forks 246. The sprockets 366 are also idlers mounted on stub shafts 377 and extending between the arms of forks 105 378 that carry said stub shafts. These forks 378 are secured to or formed integrally with arms 379 having pin and slot connections 380, 381 with the side plates 21 and being adjustably mounted in guides 382 secured to or formed integrally 110 with said side plates at the lower forward portions thereof.

95 Each set of sprockets 363, 365, 366 is thus disposed in triangular relation on one of the frames 21, and the chains passing over the sets 115 of sprockets travel over the curved guides 364 and are thus curved upwardly and forwardly from the pack feeder to the sheet receiving means hereinafter described. It will appear, from the foregoing, that the sheet conveying 120 mechanism is driven continuously through the described connections for the chains 238 with the continuously driven shaft 66, and that the chains 238 and the sprockets 363, 365, 366 are adjustable toward and away from each other 125 with the side plates 21 to accommodate sheets of various sizes. In order to provide these adjustments for the chains 238 and at the same time maintain them in driving relation with the shaft 37, the latter is provided longitudinally 130 thereof with a key-way 383 which receives keys or other suitable devices for securing the sprockets 363 to the shaft 37. The spline connections thus formed between the shaft 37 and the sprockets 363, enable the latter to be moved toward and away from each other on said shaft and at the same time provide for driving of said sprockets by said shaft. The adjustments of the side plates 21, chains 238, and sprockets 363, 365, 366, inwardly and outwardly to accommodate various sizes of sheets may be made by any suitable means for this purpose. As herein shown, said adjustments are preferably made by a hand crank 383^a secured on one part 383^b of a two part shaft. The other part of said shaft 140 is indicated at 383^c, and said shaft parts are oppositely threaded respectively and secured together by a coupling 383^d. The shaft part 383^b extends through a tube 383^e secured in any suitable manner to one of the side plates 21, and 145 15

- said shaft part has threaded engagement with the inner wall of said tube. The shaft part 383^c extends through a similar tube 383^f secured in any suitable manner to the other side plate 21, 5 and said shaft part has threaded engagement with the inner wall of said tube. 80
- As shown in Fig. 19 of the drawings, the hook carrying chains 238 of the sheet conveying mechanism, which advance the sheets upwardly 10 and forwardly along the anti-friction strips 24, are roller chains and may, if desired, be supplemented by endless driven belts, one of which is indicated at 384. In this case, each of the side plates 21 is formed with an upwardly 15 and forwardly curved guide 385 for the corresponding belt 384, the belt extending along said guide between the anti-friction strip 24 and an inner upwardly extending edge 386 of said guide. The adjacent chain 238, in the form shown in 20 Fig. 19, extends below the belt 384, and the guide 384 for the rollers 238' of said chain is secured to or formed integrally with the guide 385 for the belt 384. Each of the belts 384 engages the sheet on the underside thereof and 25 assists the hooks 237 of the chains 238 to advance said sheets along the strips 24. The belts could be driven in any suitable manner as, for example, by pulleys (not shown) mounted on the shafts 37 and 377, and on the sleeve 245. 30
- The sheets are delivered by the chains 238, over a feed board 387 to the printing press or other sheet receiving means to be fed. This feed board is bolted or otherwise suitably secured to the upper side members 44, 47 of the frames 35 40, 41, and extends transversely of said frames at the rear upper portions thereof. The sheets preferably pass from the chains 238 over curved guide members 388 and 389 which are inclined downwardly and forwardly of the strips 24. 40
- These guide members rest on the feed board 387 and support the sheets above the same. The sheets could, however, pass from the chains 238 directly over the feed board 387, if desired. The rear ends of the guide members 388 are secured 45 at 26 to the side plates 21 of the frame 20, and the forward ends of said guide members are secured by clips 390 to the guide members 389. The guide members 388 extend between the guide members 389 in overlapping end-relation there- 50 with, the guide members 389 extending forwardly of the guide members 388 and having their front ends resting on the feed board 387 adjacent feed and drop rollers comprising sheet receiving means and which will be hereinafter 55 described.
- As the sets of hooks 237 of the chains 238 successively approach the guide members 388, rocking fingers 393, movable in a slot 394 on the rear edge of the feed board 387, engage each sheet 60 on the rear edge thereof and push it across the guide members 388, 389, with an accelerated motion, so that the hooks 237 are disengaged from the sheets and can turn around the sprockets 363 and travel downwardly and rearwardly with the chains 238 to receive another sheet. These fingers 393 are preferably operated through the medium of the following devices. Fixed on the cam shaft 69 is a cam 394 (Figs. 6 and 21) which engage a roller 395. This roller 395 is 65 journaled on a fork 396 secured or formed integrally with a link 397 at the lower end thereof. The fork 396 straddles the shaft 69, and the link 397 carrying said fork extends upwardly from said shaft and is pivotally connected at 70 398 with the free end of an arm 399. This arm 75
- 399 is fixed on a sleeve 400 loosely mounted on one part 400^a of a telescopic stay shaft extending transversely of the frame 20 and secured to the side plates 21 thereof at 400^b. The shaft part 400^a extends within the other shaft part 400^c and is secured thereto by a set screw 400^d. Fixed on the sleeve 400 is a bell crank 401, one arm 402 of which is pivotally connected at 403 with the rear end of a spring pressed rod 404. The forward end of the rod 404 extends loosely through a suitable opening formed in a bracket 405 that is secured to or formed integrally with one of the side plates 21 at the front thereof. The spring 406 for the rod 404 is mounted thereon between the bracket 405 and a collar 407 which is adjustably mounted on said rod and secured thereto in any suitable manner. It will appear, from the foregoing, that the sleeve 400 and the bell crank 401 are rocked continuously by the cam operated rod 397 and the spring 95 pressed rod 404. 90
- The arm 408 of the bell crank 401 has adjustably connected thereto, at 409, the rear end of a link 410. The forward end of this link 410 is pivotally connected at 411 with one of the rocking fingers 393. The fingers 393 are secured to, and adjustable along, a rock shaft 412 which is journaled in suitable bearings provided by brackets 413. These brackets 413 are mounted on, and adjustable along rods 414 carried by the 105 side plates 21 of frame 20 and projecting forwardly thereof between the upper rear portions of the frames 40, 41. The rods 414 extend transversely of, and are mounted on, the parts 415, 416 of a telescoping shaft, and may be adjusted 110 forwardly and rearwardly to various positions and secured to said parts in openings therein, as by set screws 417. The telescoping shaft 415, 416 extends transversely of the plates 21 of frame 20, and the parts of said shaft are provided at the outer ends thereof with threaded shanks 418 which extend through suitable openings in the plates 21 to receive nuts 419 or other suitable fastening devices for securing the shaft parts 415, 416 to said plates. The shaft part 120 416 is of tubular form at its inner end and telescopes a reduced extension 420 of the shaft part 415. This construction enables the shaft parts 415, 416 and the rods 414 to be adjusted toward and away from each other along the 125 rock shaft 412 when the side plates 21 of the frame 20 are adjusted toward and away from each other as before described. The shaft part 416 has threaded through the tubular portion thereof a set screw 421 that engages the extension 420 of shaft part 415 and thus secures 130 said parts together. 130
- The fingers 393 are secured to the shaft 412 by set screws 422 that may be loosened to enable the fingers 393 to move along the shaft 412 135 when the shaft parts 415, 416 and the side plates 21 are adjusted relatively. The connections 409 and 411 are preferably of the slot or swivel type enabling the aforesaid adjustment of the fingers, shaft parts, and side plates, as described. The 140 rods 414 have secured to or formed integrally therewith outwardly and horizontally extending arms 423 having pin and slot connections 424, 425 (Figs. 18 and 20) with brackets 426 that are secured to or formed integrally with the side 145 plates 21 and project inwardly therefrom at the upper rear corners of the same. The arms 423, brackets 426 and shaft parts 415, 416 serve to support the rods 414 and retain them horizontally in parallel relation, as clearly shown in the 150

drawings, and the shaft 415, 416, the rods 414, and the rock shaft 412 comprise a substantially rectangular frame the parts of which are adjustably connected together and supported on 5 the side members 21.

The operating means for the fingers 393 is so timed with respect to the operating means for the chains 238, that when a sheet is advanced over the guides 388, 389, the fingers 393 will 10 be moved upwardly and forwardly to engage the rear edge of the sheet and push it with accelerated motion clear of the set of hooks 237, as before described. Thereafter the fingers 393 are moved rearwardly and downwardly, and 15 when the next sheet is pushed across the guide members 388, 389 by the sheet conveying mechanism, said fingers will again move upwardly and forwardly into engagement with the rear edge of said sheet and push it with accelerated motion clear of the set of fingers 237, as in the 20 case of the preceding sheet. These operations are repeated continuously in the transfer of the sheet from the sheet conveying mechanism to the guide members 388, 389, and as each sheet 25 is moved across said guide members by the fingers 393, the leading edge of the sheet passes between a feed roller 427 and drop rollers 428 that act to deliver the sheet to the printing press or other instrumentality to be fed. As herein shown, the rollers 427, 428 comprise the sheet 30 receiving means or mechanism per se, but said means or mechanism may be constituted by any machine or instrumentality to which it is desired to feed sheets, and said rollers may be 35 employed to feed the sheets to said machine or instrumentality.

The feed roller 427 is fixed on a shaft 429 that extends transversely of the frames 40, 41 and is journaled in suitable bearings on the side members 44, 47, thereof. Fixed on one end of the shaft 429 is a sprocket 430 (Fig. 6), around which passes a chain 431 that also passes around a sprocket 432 which is fixed on the shaft 37. The feed roller 427 is thus continuously driven from the shaft 37 through the described connections therefor with said feed roller. The drop rollers 428 are journaled on the free ends of arms 433 which are fixed in spaced relation on a rockshaft 434 extending transversely of the frames 40, 41, and journaled in suitable bearings on the side members 44, 47 thereof. Fixed on the rockshaft 434, at one end thereof is an arm 435 that is pivotally connected at 436 with one of a link 437. The opposite end of the link 437 is pivotally connected at 438 with one arm 439 of a bell crank 440 that is loosely mounted on the shaft 66 between the pinion 67 and the sprocket 360.

The other arm 441 of the bell crank 440 has 60 journaled thereon a roller 442 that engages a cam 443 mounted on the shaft 69 and rigidly secured to the cam 325. The roller 442 is continuously maintained in engagement with the cam 443 by a spring 444 having one end connected to the bell crank arm 439 below the pivotal connection thereof with the link 437. The opposite end of the spring 444 is connected with a pin 445 secured to the side member 12 that carries the pins 317 and 323. It will appear, 65 from the foregoing, that through the spring 444 and the cam operated bell crank 440, the link 437 is reciprocated to rock the arm 435, the shaft 434, and the arm 433, and thus move the drop rollers 428 toward and away from the feed rollers 427. The operating means for the drop 70

rollers 428 is so timed with respect to the sheet feeding and advancing means, that said rollers are raised to receive the sheets from the fingers 393 and lowered to engage said sheet with the feed roller 427 and advance it for delivery to 80 any suitable point or to a printing press or other sheet receiving instrumentality to be fed.

Loading of the pack of sheets 87 on the pack feeding and advancing mechanism, and replenishing of the supply of sheets separated and forwarded therefrom, is preferably effected by a plurality of loading mechanisms or trucks indicated broadly at 445 in the drawings. These loading trucks are constructed for movement into and out of operative relation with the sheet feeding mechanism so that the latter may be operated in a substantially continuous manner for any desired length of time. The loading trucks 445 are identical in construction and operation and will now be described in detail. 95

LOADING MECHANISMS

Figs. 1a, 2, 2a, 7a, 22, 23, 24 and 26 to 34 inclusive

100

Each of the trucks 445 includes a frame comprised by vertical standards 446, 447, cross-members 448 connected with said standards at the lower ends thereof, and side frame members 449 connected with the standards at the upper ends 105 thereof. The standards 446, 447 are provided on the lower ends thereof with forks 450 in which are journaled rollers 451 that enable the truck to be moved along the runway 8 into and out of operative relation with the pack feeder 110 through the rear thereof and between the frames 11 and the chains 84. In order to facilitate movement of the truck into and out of the pack feeder, said truck is provided with a push bar 452 that is connected with one of the cross-members 448. This push bar 452 is provided on the free end thereof with a handle 453.

The side frame members 449 of the truck, are provided longitudinally thereof with grooves 454 which receive rollers 455 that are journaled on 120 a pack holding frame or carriage indicated broadly at 456 (Fig. 22) and disposed between said side frame members for sliding movement therewith in the grooves 454. During loading of the truck, and movement of the same into 125 operative relation with the feeder, the frame or carriage 456 is retained against movement along the side members 449 by pins 457 which are fitted in openings in said side frame members and the adjacent ends of the rollers 455. These pins 130 457 are secured to chains 458 which, in turn, are secured to the side frame members 449 and thus serve to prevent the pins 457 from being lost or misplaced. The slidable pack holding frame 456 is open at the front thereof, and the 135 side members 459 of said frame are provided therein with grooves 460. The frame 456 is closed at the rear thereof by a cross-member 461 secured to or formed integrally with the side frame members 459. Journaled on the side 140 frame members 459 are rollers 462, 463 which extend across the grooves 460, and below the top of said side frame members. The rollers 463 constitute fulcrums for a frame indicated broadly at 464 (Fig. 22) and having side members 145 465 which extend in the grooves 460 of frame members 19 and engage the rollers 463. The front of the frame is closed by a cross-member 466 secured to or formed integrally with the side members 465 and projecting thereabove to pro- 150

vide a stop 467. The rear of the frame 464 is closed by a cross-member 468 secured to or formed integrally with the side members 465. This cross-member 468 is provided centrally 5 thereof with a downwardly depending curved portion 469 the upper edge of which is engaged by a cam 470 that is rotatably mounted on a shaft 471. This shaft 471 extends rearwardly of the frame member 461 and is secured in a 10 suitable opening therein by a set screw 471'. Mounted on a reduced rear end portion 472 of the hub of the cam 470, and rigidly secured thereto, as at 473, is a hand wheel 474 for turning the cam 470 on the curved portion 469 of frame 464 to thus rock said frame up or down, as desired, about the fulcrums provided by the 15 rollers 463. In order to quickly disengage the cam 470 from the frame 464 and thus enable said frame to drop down into engagement with the rollers 462, the cam 470 may be moved rearwardly on the shaft 471 by the hand wheel 474, this rearward movement of the cam and hand wheel being limited by a collar 475 secured on the shaft 471 at the rear end thereof.

20 Mounted on the frame or carriage 456 is a pack holder indicated broadly at 476 and having a base 477 and upwardly and rearwardly inclined arms 478. This pack holder extends transversely of the truck over the frame members 449 and the frames 456 and 464, the base 477 of the pack holder having openings therein for machine screws 479 or the like by which said pack holder is secured to the side members 459 of the frame 456. The pack holder 476 is preferably made in two parts that are relatively adjustable to enable said holder to accommodate sheets of various sizes. One part of the pack holder is comprised by the base 477 and the arms 478. The other part of said pack 25 holder is comprised by a cross-member 479' having secured to or formed integrally therewith arms 480 which are mounted on the arms 478 in guides 481 provided thereby. The arms 480 are provided longitudinally thereof with slots 482 through which extend bolts 483 that are mounted in suitable openings in the arms 478. These bolts 483 have threaded thereon wing nuts 484 by which the arms 480 are clamped on the arms 478. When the wing nuts 484 are loosened, the 30 upper part of the pack holder comprised by the cross-member 479' and the arms 480 may be moved vertically to any desired position of adjustment on the arms 478, whereupon the wing nuts 484 are tightened to retain the upper part of the pack holder in said position. The upper and lower part of the pack holder could also be adjusted relatively by gearing, such as embodied in the pack holder 476' shown in Figs. 7a, 23 and 24 and including a shaft 484^a having hand-wheels 484^b fixed thereon. The shaft 484^a is journaled on the arms 478 and carries pinions 484^c meshing with racks 484^d on the arms 480. The upper part of the pack holder may thus be moved up or down on the lower part thereof, by turning the shaft 484^a in one direction on the other through the medium of the hand-wheels 484^b. A suitable scale 484^e could, if desired, be provided on the pack holder to indicate various heights of sheets and corresponding settings of the parts of the pack holder, and accidental relative displacement of the parts of said pack holder could, if desired, be prevented by a pawl 484^f pivoted on one of the arms 478 and removably engaged with a ratchet 484^g fixed on 35 the shaft 484^a. Extending through threaded openings in the lower portions of the arms 478 are screw shafts 485. Fixed on these screw shafts rearwardly of the arms 478 are hand wheels 486. Pivoted mounted on the screw shafts 485 forwardly of the arms 478 are toggle members 487. These toggle members 487 have secured thereto in any suitable manner a follower strip 488 movable to various positions of adjustment by the screw shafts 485 and the hand wheels 486. Extending through suitable threaded openings in the upper portions of the arms 480 are screw shafts 489 which have threaded engagement with the walls of said threaded openings. Fixed on the screw shafts 489 rearwardly of the arms 480 are hand wheels 490. Mounted on the screw shafts 489 forwardly of the arms 480 is a follower plate 491. This follower plate 491 has bolted or otherwise suitably secured thereto, as at 492, brackets 493. The shafts 489 project through suitable openings formed in the brackets 493, and the follower plate 491 is secured on said shafts by collars 494 housed in the brackets 493 and receiving the forward ends of the screw shafts 489. These collars are rotatable in the brackets 493 when the shafts 489 are turned by the hand wheels 490, and said collars are secured to said shafts by pins 495 or other suitable fastening devices. It will thus appear that the follower plate 491 may be adjusted to various positions 40 by turning the screw shafts 489 with the hand wheels 490. The follower plate 491 is provided with a flange 496 bent rearwardly and upwardly from said plate and forming a seat 497 at the junction of the flange with the follower plate. 45 Bolted or otherwise suitably secured, as at 498, on the flange 496 of follower 491, are brackets 499 provided on their upper ends with apertured bosses 500. Journaled in the bosses 500 are shafts 501 the ends of which are bent angularly 50 to form stops 502. Fixed on the rear ends of shafts 501 are hand wheels 503 and collars 504. Mounted on the shafts 501 are springs 505 corresponding ends of which bear against the collars 504. The opposite ends of the springs 505 55 bear against pulleys 500^a or the like keyed on the shafts 501 in slots 500^b therein and mounted on said shafts between said springs and the bosses 500. The shafts 501 may thus be moved longitudinally through the pulleys 500^a and the bosses 500, and passing around said pulleys is a crossed endless element 500^c which, when one of the shafts 501 is turned in one direction, acts to turn the other shaft 501 in the opposite direction, the stops 502 being swung in one direction or another in accordance with the direction of rotation of said shafts.

60 In order to load the truck with a pack of tin sheets 87 or the like, the sliding frame 456 is locked to the side frame members 449 of said truck by the pins 457, and the frame 464 is rocked on rollers 463 by the hand wheel 474 and the cam 470 to depress the rear end of frame 464 and elevate the front end thereof. The frame 464 is then locked in inclined position by an apertured block 507 which is engaged over a pin 508 on the member 468 of frame 464. The block 507 is pivoted at 509 on a link 510 which, in turn, is pivoted at 511 on a handle 512. This handle 65 512 is pivoted at 513 on a bracket 514 secured to or formed integrally with the frame member 461 and projecting rearwardly therefrom. The bracket 514 is provided with a stop 515' to engage and support the handle 512 in inoperative 70 75 80 85 90 95 100 105 110 115 120 125 130 135 140 145 150

position when the block 507 is disengaged from the pin 508.

The follower members 488 and 491 are adjusted by the hand wheels 486 and 490, respectively, 5 so that the lower member 488 is slightly in advance of the upper member 491. The stops 502 are then turned up to inoperative positions by the hand wheels 503, whereupon the pack of tin sheets 87 or the like is placed on the side members 465 of frame 464 and rests in inclined position 10 against the follower members 488 and 491 with the lower portion of the pack engaged between the stop 467 and the follower member 488. The sheets 87 of the pack thus stand on edge 15 one behind another on the side members 465 of frame 464, and when the pack has been positioned on said frame, as aforesaid, the stops 502 are turned down by hand wheels 503 into engagement with the pack at the top and front 20 portion thereof. The springs 505 provide for yielding movement of the stops 502 when they are turned into engagement with the pack, and the upper portion of said pack is thus yieldably clamped to a slight degree between the stops 25 502 and the follower member 491. After the pack of sheets has been positioned as aforesaid, and the block 507 engaged over the pin 508, the lever 512 is pulled rearwardly, there- 30 by imparting slight movement to the frame 465 so that the sheets of the pack are compressed or gathered tightly to the desired degree between the stop 467 and the stop 488. Gathering of the sheets in this manner, insures that during each 35 cycle of operation of the machine there will be one sheet separated and forwarded from the pack by the means heretofore described for this purpose.

Assuming that the pack feeder has not been started, and is to receive an initial supply of 40 sheets loaded on one of the trucks 445, as above described, a pawl 506 (Fig. 8) that normally engages a ratchet 507' to prevent accidental movement of the sleeves 148 and parts carried thereby, along the standards 149, is disengaged 45 from said ratchet. The pawl 506 is pivoted at 508' on one of the bosses 159, and the ratchet 508' is fixed on shaft 160. When said pawl is disengaged from said ratchet, the set screw 179 is loosened, and the hand wheel 163 is turned 50 to rotate shaft 160 so that it moves along standards 149 to bring the stops 144 and the detector 55 fingers 187 in proper position to engage the front, upper portion of the supply or pack of sheets to be loaded on the feeder. The pawl 506 is then engaged with the ratchet 507', and set screw 179 is tightened, whereupon stops 138, 139, 144 are adjusted to engage the pack of sheets at the four front corners thereof, as previously described.

60 The detector fingers and stops having been adjusted properly, the pawl 231 is disengaged from ratchet 98 and the pawl 96 (Fig. 7) is lifted to an inoperative position by pawl lifter 509', whereupon the slides 101 and the parts 65 carried thereby are moved rearwardly by hand until the follower plate 88 is positioned a distance from the stops 144 corresponding with the thickness of the supply of sheets to be loaded on the feeder. When the slides 101 and the 70 parts carried thereby are moved rearwardly, as described, the racks 100 turn the gears 99 and the shaft 94 idly in a counter-clockwise direction (Fig. 7).

A pawl 510' (Fig. 7) that normally engages a 75 ratchet 511' to prevent accidental displacement

of the brackets 115 and the parts carried thereby, along the standards 110, is then disengaged from said ratchet. The pawl 510' is pivoted at 512' on one of the bosses 114, and the ratchet 511' is fixed on the shaft 113. When pawl 510' is disengaged from ratchet 511', a hand wheel 513' is turned to rotate shaft 113 so that it moves upwardly on standards 110 to raise the follower plate 88 a sufficient distance to enable the pack of sheets to be run into the feeder under said plate.

The parts of the feeder having been adjusted and set, as described, the pins 457 (Fig. 22) are pulled out to unlock the carriage 456, and the truck 445 carrying a pack of sheets is run into 90 the feeder from the rear thereof between the frames 11 and the chains 84 and along the way 8, until the wheels 451 are received in recesses 8' and the front extremities of the truck frame members 449 abut the rear ends of the guide 95 bars 117 (Fig. 11). The grooves 118 of the guide bars 117, and the grooves 454 of the truck frame members 449, are thus brought into alignment, whereupon the movable carriage 456 is pushed forwardly along the truck frame members 449 100 and the guide bars 117, the rollers 455 traveling along the grooves 118, 454, and the movable carriage 456 being stopped when the pack of sheets passes over the wedge-shaped blocks 128, 129 and engages the stops 138, 139, 144, and the 105 detector fingers 187.

The hand wheel 474 and the cam 470 are then turned to lower the frame 464 and the pack of sheets 87, so that said frame rests on both the rollers 462 and 463, and said pack of sheets rests 110 upon and is supported by the wedge-shaped blocks 128, 129 and the chains 84. The slides 101 are then moved manually to position the plate or follower 88 in vertical alignment with the space between the back of the pack and the 115 flange 496 of the follower member 491. The hand wheel 513' is then rotated to lower the follower plate 88 between the back of the pack of sheets and the front of the flange 496 of follower member 491 until the vertical portions of 120 bayonet slots 514' (Fig. 22) of said plate are engaged over the shafts 501. The shafts 501 are then turned to bring the stops 502 into alignment with the horizontal portions of slots 514', whereupon the shafts 501 and the stops 502 are 125 pulled rearwardly of plate 88 and it is moved further downwardly by handwheel 513' until the lower edge of the plate 88 engages the seat 497 at the junction of follower member 491 with flange 496 thereof. The carriage 456 and parts 130 carried thereby are then moved rearwardly along the guide bars 117 onto the side members 449 of the truck 445. The truck is then moved out of the feeder through the rear thereof, between the frames 11 and the chains 84 and 135 along the way 8, and may again be loaded with a supply of sheets, as above described. The pawl 231 is then engaged with the ratchet 98 and the pawl lifter 509' is moved so that the pawl 96 may engage said ratchet. The feeder 140 is then ready for operation. When the feeder has been initially loaded, as above described, and is ready for operation, the switch 61 is actuated to start the motor 54 and the various instrumentalities connected therewith and including the pack feeder, the sheet separating and forwarding devices, the sheet conveyor, and the feed and drop rollers. These instrumentalities then act on the sheets as previously 145 described.

Assuming that the feeder has been operated for a sufficient length of time to nearly exhaust the supply of sheets thereon, and that it is desired to reload the feeder while the latter and the associated mechanisms are in operation, one of the trucks 445, loaded as before described, is run into the feeder after the pins 457 have been pulled out to unlock the frame 456. When the last named truck is run into the feeder, the forward end of the truck frame members 449 will engage the rear ends of the guide bars 117, as previously described, whereupon the follower plate 88 is raised slightly by the hand wheel 513', to bring the vertical portions of bayonet slots 514' into alignment with stops 502. The carriage 456 and the pack of sheets carried thereby is then moved along the truck frame members 449 and the guide bars 117 until the stops 502 pass through the vertical portion of bayonet slots 514' of follower plate 88 and engage the back of the nearly exhausted supply of sheets on the feeder. At this time, pawls 513, 516 (Fig. 22) which have previously been raised to inoperative positions, are lowered into engagement with the moving chains 84, and the carriage 456 and supply of sheets carried thereby will therefore be advanced by said chains with the nearly exhausted supply of sheets supported by the latter and the follower plate 88. The pawls 515, 516 are pivotally mounted at 517 on vertical extensions 518 of brackets 519 secured to or formed integrally with the base plate 477 and projecting rearwardly therefrom as clearly shown in Fig. 22 of the drawings. These pawls 515, 516 are connected together by a rod 520 provided at one end with a handle 521 through the medium of which said pawls may be lowered into engagement with the chains 84, or raised to inoperative position, as desired.

The new supply of sheets having been run into the feeder, as described, the hand wheel 513' is rotated to raise the follower plate 88 above the new supply of sheets, as clearly shown in Fig. 2 of the drawings. The pawl 96 (Fig. 7) is then lifted and supported out of engagement with the ratchet 98 by the pawl lifter 509', whereupon the slides 101 and the parts carried thereby are moved rearwardly by hand until the follower plate 88 is in vertical alignment with the follower plate 491 of pack holder 476. The hand wheel 513' is then rotated to lower the follower plate 88 between the back of the new supply of sheets and the flange 496 of follower plate 491 until the vertical portions of slots 514' are engaged over shafts 501. The shafts 501 are then turned to bring the stops 502 into alignment with the horizontal portions of slots 514' whereupon said shafts and stops are pulled rearwardly of plate 88 and the latter is lowered to engage seat 497. The hand wheel 474 and the cam 470 are then turned to lower the frame 464 and transfer the new supply of sheets therefrom onto the moving chains 84. The pawl 510' is again engaged with the ratchet 511' and the pawl 96 is again lowered by the pawl lifter 509' for engagement with the ratchet 98, whereupon the pawls 515, 516 are disengaged from the chains 84 and moved upwardly to inoperative positions by the handle 521 and rod 520. The frame or carriage 456 and parts carried thereby are then moved rearwardly along the guide bars 117 onto the side members 449 of the truck 445 and the truck is moved out of the feeder rearwardly thereof, between the frames 11 and along the way 8, and can then

again be loaded, as before described. It will thus appear, that through the provision of the trucks 445 and the carriages 456, and the construction of the parts thereof for cooperative action with the movable parts of the feeder, that it is unnecessary to stop the feeder to reload it, and that a supply of sheets may be maintained continuously on the feeder by running trucks into and out of the same, as before described.

The loading mechanism of the embodiment of the invention shown in Figs. 23 and 24 has the same construction and operation as the loading mechanism previously described, except that the pack holder 476' (Fig. 7a) is used in conjunction with carriage 456 and a frame indicated at 516' (Figs. 23 and 24). Frame 516' is pivotally mounted on the rear of the side members 12 of frames 11 so that when the carriage 456 and the pack holder are locked to the pivotally mounted frame 516' as by the pins 457, said pivotally mounted frame and said holder and carriage may be swung to support the holder in horizontal position for loading and then swung to support the loaded holder vertically and enable the carriage and holder to be unlocked from said frame and run into the feeder.

Accordingly, the frame 516' is fixed in any suitable manner on a shaft 517' having the sprockets 85 loosely mounted thereon and extending transversely of the feeder in bearings 105 formed in the side members 12 of the frames 11 at the rear thereof. One end of the shaft 517' projects outwardly from the adjacent side member 12, and fixed on said outwardly projecting end of the shaft is a pinion 518' which meshes with a gear 519' fixed on, or formed integrally with, a hand wheel 520' provided with a handle 521' and, in turn, fixed on one end of a stub shaft 522 journaled in a suitable bearing on said side member 12. In order to load the pack holder, the carriage 456 is locked to the frame 516' by the pins 457, whereupon said carriage and said holder are turned by the hand wheel 520' to the position indicated in dotted lines at the right of Fig. 23 of the drawings. The pack holder thus extends horizontally from the rear of the feeder and may be locked against displacement, as by a pawl 523 pivoted on the side member 12 adjacent the hand wheel 520' and adapted to engage a ratchet (not shown) fixed on said wheel or on the shaft 522. In order to accommodate the pack compressing lever 512 when the pack holder is turned into horizontal position for loading, a recess 524 may, if desired, be provided in the machine foundation to receive said lever and the parts connected therewith.

When the pack holder 476' is turned into its horizontal position for loading, the stops 502 are turned outwardly and the pack of sheets is loaded on said holder in any suitable manner, or by a truck, crane, or any suitable means for this purpose. The stops 502 are then turned inwardly over the pack of sheets and act in conjunction with the plate 491, the carriage 456, and the strip 488, to prevent displacement of the sheets from the pack holder. The frame 516' and the loaded pack holder 476' and carriage are then turned by the hand wheel 520' to their full line positions shown at the right of Fig. 23 of the drawings, and the pack is raised and compressed by the cam operated lifting frame 464 and the pack compressing means including the lever 512, in the manner pointed out in connection with the first described em-

bodiment of the invention. The hand wheel 520' is then locked against rotation by the pawl 523 and the pins 457 are disengaged from the carriage 456 to release the latter from the frame 516'. The carriage 456 and the loaded pack holder carried thereby, are then run into the feeder until the sheets bear against the front stops 139, 144 or against the back of the diminishing supply of sheets on said feeder. In either case, the follower plate 88 and the stops 502 are moved as previously described in order to position said plate back of the supply of sheets, whereupon the sheets on frame 464 are lowered thereby onto the feed chains 84, and the carriage 456 and pack holder 476' are moved rearwardly of the feeder onto the frame 516' and locked thereon. Loading or reloading of the feeder may thus be accomplished whenever desired, by operation of the frame 516', the carriage 456 and the pack holder 476', as just described.

In the embodiment of the invention shown in Figs. 26 to 28, inclusive, the loading mechanism is comprised by a pack holder indicated broadly at 525 (Fig. 28) and including L-shaped brackets having arms 526 and 527, the latter being connected together by a cross member 528. This pack holder 525 is journaled on the stub shafts 86, the sprockets 85, in this case, being fixed on said stub shafts to drive the latter when the chains 84 are driven by the described mechanism for this purpose. Rigidly secured to the hubs 529 of the L-shaped brackets 526, 527, are clutch members 530 which are adapted to be engaged by clutch members 531 keyed to and slidably along the stub shafts 86. The clutch members 531 are provided with collars 532 in grooves of which are engaged forked levers 533 and 534 journaled in any suitable manner on the side members 12 of frames 11. The lever 534 has pivotally connected therewith one end of a link 535 the opposite end of which is pivotally connected with an arm 536 of the lever 533. This lever 533 is also provided with an arm 537 the free end of which has pivotally connected therewith one arm 538 of an L-shaped foot lever the other arm 539 of which extends outwardly through an opening 540 formed in one of the legs 15' of the innermost side member 12. The innermost side members 12 of frames 11 are, in this case, shorter than the outer side members thereof to enable a truck with a load of sheets to be run a short distance into the feeder frame for loading of the sheets on the holder 525, as hereinafter described.

The clutch parts 530, 531 are normally maintained out of engagement by coil springs 541 (Fig. 27), and when it is desired to load the feeder, the holder 525 is swung about the stub shafts 86 to position the arms 527 horizontally as shown at the right of Fig. 26 of the drawings, where said holder is supported, in any suitable manner, to maintain the arms 526 in vertical and horizontal positions, respectively. A truck 542, the wheels of which are indicated at 543, is provided with skids 544 on which the pack of sheets is placed prior to running the truck into the feeder. The loaded truck 542 is then run into the feeder, as shown in Figs. 26 of the drawings, so that the arms 527 extend under the pack of sheets between the skids 544, and the front side of said pack engages the arms 526. A second pack holder is then positioned at the rear of the feeder to receive the pack of sheets from the holder 525, and in the embodiment of the

invention now being described, this second pack holder is comprised by a follower plate 545 (Figs. 26 and 27) and a carriage 546 (Figs. 26, 27 and 31). The plate 545 is slidably mounted on standards 547 and carries a shaft 548 provided with a hand wheel 549 and pinions 550 engaging racks 551 formed on said standards.

The plate 545 has pivoted thereon a pawl 552 which may be removably engaged with a ratchet 553 fixed on the shaft 548. The plate 545 also carries sheet stops 554 rotatably and slidably mounted thereon and the shafts 555 of which are provided with hand wheels 556 and collars 557. Springs 558 are mounted on the shafts 555 between the collars 557 and bearings 559 for said shafts. The standards 547 are mounted on bars 560 slidably in guides 561 provided with anti-friction bearings 562 (Fig. 31), said guides being secured to or formed integrally with brackets 562' which, in turn, are bolted or otherwise suitably secured to the outermost side members 12 of the feeder frames 11.

The carriage 546 is comprised by side members 563 connected together by a pivoted plate 564 and a clamping stop 565 provided with arms 566 slidably mounted on cams 567 and rollers 567' journaled in side members 563 and extending in grooves 568 thereof into which the arms 566 also extend for engagement with said rollers. The operating handles for cams 567 are indicated at 567'' and the arms 566 are provided with curved ends 569 adapted to be engaged by cams 570 fixed on stub shafts 571 provided with cam operating handles 571' and journaled in suitable bearings in brackets or extensions 572 formed on the side members 563 rearwardly thereof. The side members 563 have journaled thereon rollers 573 extending in suitable grooves in tracks 574 bolted or otherwise suitably secured to the innermost side members 12 of frames 11. The tracks 574 extend substantially the entire length of the feeder, and the carriage 546 and the follower plate 545 may, through the provision of said tracks and the guides 561, be moved independently, or as a unit, in opposite direction along said feeder, as desired.

The arms 526 and 527 having been swung to vertical and horizontal positions respectively, as previously described, and the loaded truck 542 having been run into the feeder so that the pack of sheets extends over arms 527 and the front side of said pack engages arms 526, the plate 545 and the carriage 546 are run rearwardly to receive the pack, the plate 545 and the stops 554 at this time being raised upwardly on the standards 547 a sufficient distance to clear the pack when it is transferred from the truck 542 to the feeder, as will now be described.

Assuming that the feed chains 84 are being operated, the foot lever 538, 539 is depressed to engage the clutch parts 530, 531, swing the holder 525 and the pack of sheets thereon upwardly to their dotted line positions shown in Fig. 26 of the drawings, and thus position said pack for loading on the carriage 546. The foot lever 538, 539 is then released at which time the plate 545 and the stops 554 are moved into engagement with the pack as shown in dotted lines in Fig. 26. The plate 564 is then turned into engagement with the rear of the pack, and the cams 567, 570 are turned by their operating handles 567'', 571' to move the arms 566 and the stops 565 rearwardly and upwardly about the rollers 567' and thus lift the pack off the arms 526. The carriage 546 and the plate 545, with

the pack clamped therein, are then run rearwardly a short distance clear of the arms 526, 527 whereupon said plate and the stops 554 are further lowered over the top of the pack. The 5 holder 525 may then be swung rearwardly and downwardly for reloading, and the carriage 546 and the plate 545, with the pack of sheets clamped thereon are run forwardly against the sheet stops 139, 144 or against the back of a 10 diminishing supply of sheets engaged therewith. In either case, the follower plate 88, previously lifted and run rearwardly, is lowered back of the supply of sheets between the latter and the plate 545 and the stops 554 are turned and pulled rearwardly of the plate through the slots 514' thereof. The plate 88 is then lowered to operating position back of the supply of sheets, whereupon the cams 567, 570 are turned to lower the arms 566 and the sheets carried thereby so that the latter rest on the chains 84. The 20 plate 545 and the carriage 546 are then run rearwardly for reloading.

The loading mechanism of the embodiment of the invention shown in Figs. 29 and 30, has the 25 same construction and operation as the loading mechanism shown in Figs. 26 to 28, inclusive, except that the pack of sheets 87 is delivered by a truck 575 onto a pair of stationary arms 576 from which the pack is lifted onto the carriage 546 and carried into the feeder by said carriage and the plate 545. The arms 576 are secured to or formed integrally with the innermost side members 12 of the frames 11, and said arms project rearwardly from said frames and have upturned retaining lugs 577. The tracks for the carriage 546 and the guides for the plate 545, are indicated at 578 and 579, respectively. Said tracks and guides are secured to the inner and outer side members 12 respectively of the feeder frame 11 in any suitable manner and project rearwardly therefrom beyond the arms 576, as clearly shown in Fig. 29 of the drawings.

A platform 580 provided with legs 581 is initially positioned on the floor or machine foundation and loaded with two packs of sheets 87 the lower edges of which rest on skids 581' placed on said platform. The inner opposed sides of the two packs of sheets rest against a cross bar 582 mounted in any suitable manner on the 45 upper ends of inclined standards 583 the lower ends of which are anchored in sockets 584 that are bolted or otherwise suitably secured to the platform 580. The two packs of sheets having been loaded on the platform 580 to stand thereon in inclined positions, as shown in Fig. 29 of the drawings, the truck 575, which is of any suitable or well known "lifting jack" type, having wheels 575', is run under said platform, whereupon the lifting elements of the truck are 50 actuated to lift said platform and the two packs of sheets carried thereby.

The plate 545 is then run rearwardly and, with the stops 554, elevated sufficiently to clear the top of the sheet supply on truck 575. The 55 loaded truck 575 is then run into the feeder between the tracks 578 at which time the skids 581 supporting the front pack of sheets are displaced from below the same to drop said pack onto the arms 576 and in front of the lugs 577. While transferring the pack of sheets onto arms 60 576, the plate 545 is lowered to engage the back of the pack and the stops 554 are engaged with the front of said pack at the top thereof. The plate 545 and the arms 576 thus support said 70 pack at the top and bottom thereof, and the

truck 575 is run out of the feeder leaving a pack of sheets standing on the arms 576 and resting against the plate 545. The carriage 546 is then run rearwardly along the tracks 578 under the transferred pack of sheets 87, and the plate 564 is turned up against the back of said pack. The cams 567, 570 are then turned to move the members 566 and the clamping stop 565 rearwardly and upwardly about rollers 567' so that the pack of sheets is lifted from the arms 576 and clamped on the carriage 546. The plate 545, carriage 546, and pack of sheets thereon are now moved into the feeder until the sheets bear against the stops 139, 144 or the back of a diminishing supply of sheets engaged therewith. In either case, the follower plate 88 and the stops 554 are moved, as previously described, and the follower plate 88 engaged behind the supply of sheets. The cams 567, 570 are then 80 operated to lower the arms 566 and thus transfer the sheets therefrom onto the chains 84. The carriage 546 and the plate 545 are then 85 run rearwardly of the feeder for reloading by the truck 575 with the pack of sheets 87 left on the platform 580 when the first pack was 90 removed therefrom. In order to load the second pack on the carriage 546, the truck 575 must, of course, be moved out of the feeder, turned around and then run into the feeder. Each time a pack of sheets is removed from the truck 95 575 and the latter is run out of the feeder, turned around and run into the feeder, a pack of sheets may be loaded on said truck. The operation of the feeder, is otherwise the same as set forth in connection with the embodiment of 100 the invention shown in Figs. 26 and 27.

The loading mechanism of the embodiment of the invention shown in Figs. 32 to 34 inclusive, has the same construction and operation as the loading mechanisms shown in Figs. 23, 24 and 26 to 27, inclusive, except that it is comprised by a carriage 585 and a pack holder 586 provided with operating mechanisms hereinafter described and by which the carriage and holder have various movements imparted thereto in order to 105 receive the sheets and deliver them to the feeder. The carriage 585 is comprised by blocks 587 slidably mounted in guides 588 formed in, and extending longitudinally of, the innermost side members 12 of frames 11. The blocks 587 are 110 connected together by a shaft 589 journaled in suitable bearings in said blocks and provided with gears 590 which mesh with racks 591 extending longitudinally of the feeder in parallel 115 relation with the guides 588.

The racks 591 are secured in any suitable manner to extensions 592 of webs 593 formed on the innermost side members 12 of frames 11, certain of the webs 13 (Fig. 11) in this case being eliminated to facilitate movement of the carriage 585 along said frames. The shaft 589 has fixed thereon a handle 594 by which said shaft and the gears 590 may be rotated to move the carriage 585 longitudinally of the feeder along the guides 588. When the handle 594 is turned, the gears 590 travel along the racks 591 and thus move the carriage, comprised by blocks 587 and shaft 589, along the guides 588 in accordance with the direction of rotation of said shaft in said blocks.

The pack holder 586 is comprised by a pair of L-shaped brackets 595 rigidly secured on a cross shaft 596 and having arms 597 and 598. The cross shaft 596 forms part of the carriage 585 and is journaled in suitable bearings in the 140 145 150

blocks 587 thereof. The arms of the brackets 595 are connected together by cross webs 599, 600 and 601 and the arms 598 are provided with sheet retaining lugs 601'. Mounted in suitable 5 bearings in the free ends of the arms 597 are shafts 602 that are slideable and rotatable in said bearings and normally retained against displacement therein by set screws 603. The rods 602 have rigidly secured on corresponding ends 10 thereof small hand wheels 604, and said rods have removably secured on the opposite ends thereof pack retaining stops 605.

Secured in any suitable manner to, or formed integrally with, one of the blocks 587 is a forked 15 bracket 606 having arms 607 provided with bosses 607' in which is journaled a stub shaft 608 having fixed thereon a hand wheel 609. The shaft 608 also has fixed thereon, between the bosses 607', a worm gear 610 which meshes 20 with a worm wheel 611 that is fixed on the cross shaft 596. It will thus appear the gearing connecting shaft 608 and shaft 596 will rotate the latter and swing the pack holder on the carriage 586 when the hand wheel 609 is rotated.

25 When loading the feeder by the loading mechanisms just described, the handle 594 is turned to run the carriage 585 to the rear or loading end of the feeder. The hand wheel 609 is then turned to swing the pack holder 586 to its loading position indicated in dot and dash lines at the right of Fig. 32 of the drawings, wherein it will be noted that the arms 597 and 598 extend horizontally and vertically, respectively. If the pack holder 586 is to be loaded by hand 30 or crane, the set screws 603 are loosened and the rods 602 and the stops 605 are displaced so that said rods depend from the arms 597 when the pack holder is turned to its loading position. A supply of sheets 87, piled one on another, 40 is then positioned on the arms 597 against the arms 598, and under the lugs 601', whereupon the hand wheel 609 is turned to swing the loaded holder 586 to the dotted line position thereof shown approximately at the center of Fig. 32 of 45 the drawings. The rods 602 and the stops 605 are then moved to engage the latter with the supply of sheets and clamp the supply on the holder, the set screws 603 at this time being tightened to prevent displacement of said rods 50 and stops.

If the pack holder 586 is to be loaded by a truck, the stops 605 are removed from the rods 602 and said rods are removed from the pack holder, before the latter is turned to the loading position mentioned above. When the pack holder is turned to said loading position, the truck and pile of sheets thereon is run into the feeder so that the arms 597 extend under the pile of sheets and the latter bears against the arms 598 and is engaged by the lugs 601'. The hand wheel 609 is then turned to swing the pack holder 586 so as to remove the pile of sheets from the truck and position said holder and sheets as indicated in dotted lines in Fig. 32 of 60 the drawings. The rods 602 and the stops 605 are then replaced to engage the latter with the sheets and clamp them on the holder, the set screws 603 at this time being tightened to prevent displacement of said rods and stops.

70 The pack holder 586 having been loaded and turned to the dotted line position shown in Fig. 32 of the drawings, the hand wheel 609 is further rotated to swing said holder and the supply of sheets thereon to a position such that the sheets 75 stand on edge one behind another on the arms

598 for delivery in similar position to the feed chains 84. The handle 594 is then turned to move to carriage 585 and the loaded pack holder 586 toward the front of the feeder and engage the supply of sheets with the stops 139, 144 or 80 with the back of a diminishing supply of sheets engaged therewith. In either case, the follower plate 88, previously lifted and run rearwardly, is lowered back of the supply of sheets between the latter and the arms 597, the vertical portions of the slots 514' of said plate at this time being engaged over the rods 602.

85 The set screws 603 are then loosened, whereupon the rods 602 and the stops 605 are turned by the hand wheel 604 and pulled rearwardly 90 of the follower plate 88, the stops 605 passing through the horizontal portion of the slots 514' of said plate. The follower 88 is then lowered to operating position back of the supply of sheets and connected with the follower operating mechanism, the hand wheel 609 at this time, being further rotated to swing the pack holder 586 so that the supply of sheets is transferred from arms 598 onto chains 84. The handle 594 is then turned to move the carriage 585 and the 100 pack holder 586 rearwardly of the feeder for reloading in the manner previously described.

OPERATION

The operation of the feeder will be clearly 105 apparent from the foregoing, and may be briefly summarized as follows. A pack of sheets 87 is carried by the described or any suitable means, into position at the rear of the feeder to be loaded thereon by loading mechanism of the 110 present invention which may be constructed and operated as previously pointed out in detail. The pack of sheets having been delivered by said loading mechanism to the feeder with the sheets standing on edge one behind another, the follower plate 88 is elevated and said pack is run 115 forwardly along the feeder by the carriage 456 and plate 491, or the carriage 546 and plate 545, or the carriage 585 and pack holder 586, until the pack of sheets engages the stops 138, 139 and 120 144, or the back of a diminishing supply of sheets standing on edge on the feeder and engaged with said stops, as the case may be. The follower plate 88 and the stops 502 or 554 are then moved, 125 as previously described, to engage said plate with 130 the back of the sheets, whereupon the sheets which have been run into the feeder are lowered onto the feed chains 84.

The carriage and plate or holder are then 135 run rearwardly of the feeder for reloading or to 130 an out-of-the-way position, and with the feeder in operation, the separating and forwarding devices 235 and 236 separate the sheets successively from the front of the supply on the feeder, by imparting buckles to each sheet successively 140 in angularly related directions and moving each sheet clear of the stops 138, 139 and 144. The separating and forwarding devices 235, 236 deliver the sheets one after another to the hooks 237 that are carried by the driven chains 238 and successively positioned thereby to receive the sheets from said separating and forwarding devices. As the latter separate and advance the sheets, the pack advancing means 84, 88 is actuated intermittently through the action of the 145 detectors 187 and the mechanism controlled thereby for operating said pack advancing means. The chains 238, in turn, deliver the sheets one after another to the printing press or other sheet receiving means, and the loading, 150

feeding, separating, and delivery operations are carried on in a substantially continuous manner through the arrangement, construction, and operation of loading, feeding, separating, and conveying mechanism embodying the present invention and, by way of example, illustrated in the accompanying drawings and herein described in detail.

While several embodiments of the present invention are herein illustrated and described with more or less particularity, it is to be expressly understood that the invention is not limited to said embodiments or otherwise than by the terms of the appended claims.

15. What is claimed is:

1. In apparatus of the character described, mechanism for supporting and advancing a supply of sheets standing on edge one behind another, means forwardly of and above said mechanism and to which sheets are fed one after another, sheet conveying means for delivering the sheets upwardly and forwardly to said first named means, and means movable toward and away from the front of said supply for separating the sheets successively therefrom and delivering them in like manner to said sheet conveying means.

2. In apparatus of the character described, means to which sheets are fed, mechanism below and rearwardly thereof for supporting and feeding a supply of sheets standing on edge one behind another, one or more oscillatory devices movable toward and away from the front of said supply for separating the sheets therefrom, and sheet conveying means receiving the sheets from said device or devices and adapted to advance the sheets upwardly therefrom for delivery to said first named means.

3. In apparatus of the character described, means to which sheets are fed, mechanism for supporting and advancing a supply of sheets standing on edge one behind another, curved sheet supporting means interposed between the means to be fed and said mechanism, sheet conveying means adapted to move the sheets one after another over said curved sheet supporting means for delivery to said first named means, and means movable toward and away from the front of said supply for separating sheets successively therefrom and delivering them one after another to the curved sheet supporting means and said sheet conveying means.

4. In apparatus of the character described, mechanism for supporting and advancing a supply of sheets standing on edge one behind another, suction means adapted to rock upwardly and rearwardly to engage the foremost sheet of the supply and to rock forwardly and downwardly to separate it from said supply and advance said sheet therefrom in inclined standing position, upwardly and forwardly curved sheet supporting means against which the inclined sheet is delivered by said suction means, and sheet advancing means arranged to travel adjacent the curved sheet supporting means and adapted to engage the lower edge of the sheet and push it upwardly and forwardly with a turning motion over said curved supporting means.

5. In apparatus of the character described, means to which sheets are fed, mechanism below and rearwardly thereof for supporting and advancing a supply of sheets standing on edge one behind another, sheet separating and forwarding means movable toward and away from the front of said supply and adapted to separate the fore-

most sheet therefrom and advance it forwardly of the supply, sheet conveying means adapted to receive the sheet from said sheet separating and forwarding means and carry it upwardly therefrom, and means movable to engage the rear edge of the upwardly moved sheet and push it with accelerated motion from the sheet conveying means to said first named means. 80

6. In apparatus of the character described, a feeder for supporting and advancing a supply of sheets standing on edge one behind another, means to which sheets are fed, means movable toward and away from the front of said supply and adapted to separate sheets successively therefrom and deliver them in like manner to said first named means, and means movable longitudinally of the feeder for delivering the supply of sheets in standing position thereon. 85

7. In apparatus of the character described, a feeder for supporting and advancing a supply of sheets standing on edge one behind another, means to which sheets are fed, one or more devices movable toward and away from the front of said supply and adapted to separate the sheets successively therefrom and forward them in like 100 manner to said first named means, and loading means movable longitudinally of said feeder for replenishing the supply of sheets thereon. 95

8. In a sheet feeder, slidably mounted means, endless means, mechanism for moving both of said means in the same direction, and a follower mounted on and movable with said slidably mounted means and adapted to engage the rear of a supply of sheets standing on edge one behind another and carried by said endless means. 105

9. In a sheet feeder, a pair of parallel shafts, means for rotating the same, gears on one of the shafts, rack bars operated by said gears and carrying a follower, and endless means operated by the other shaft and adapted to carry 110 a supply of sheets standing on edge one behind another and engaged at the rear thereof by said follower.

10. In a sheet feeder, mechanism for supporting and advancing a supply of sheets standing on edge one behind another, endless means and slidable means engaging the supply at the bottom and rear thereof respectively and forming parts of said mechanism, a pair of shafts each connected with one of said means to operate the same, a pair of interconnected pawl and ratchet mechanisms each mounted on one of said shafts and adapted to rotate the same, and means for operating said pawl and ratchet mechanisms. 120

11. In a sheet feeder, slidably mounted means, endless sheet supporting and feeding means, mechanism for normally moving both of said means in the same direction, a sheet supporting and feeding follower fixed on and movable with said slidably mounted means, and means for disconnecting said mechanism from the slidably mounted means whereby the latter and the follower may be moved independently of said endless means as desired. 135

12. In a pack supporting and advancing mechanism, spaced slidable members, vertical supports secured to said members, a follower extending between the supports and adjustably mounted thereon, and means for moving the slidable members, the supports, and said follower as a 145 unit. 140

13. In a pack supporting and advancing mechanism, spaced slidable members, vertical supports secured to said members, a follower ex- 150

- tending between the supports and slidably mounted thereon, and rack and gear means for sliding the follower vertically along said supports to any desired position of adjustment 5 thereon.
14. In a sheet feeder, means for supporting and advancing a supply of sheets standing on edge one behind another, vertical standards mounted on the feeder and between which the supply of sheets is advanced by said means, and stops for engaging the front upper corners of the supply, said stops being mounted on said standards for adjustment laterally and vertically thereon. 80
15. 15. In a sheet feeder, means for supporting and advancing a supply of sheets standing on edge one behind another, lower stops on the feeder for engaging the supply at the front lower corners thereof, vertical supports on said feeder and between which the supply of sheets is advanced by said means, upper stops on said supports for engaging the supply at the front upper corners thereof, and means providing for lateral and vertical adjustment of said lower and upper stops. 85
16. In a sheet feeder, means for supporting and advancing a supply of sheets standing on edge one behind another, supports between which the supply is advanced by said means, stop carrying means on said supports and adjustable vertically along the same, stops on the stop carrying means for engaging the front of the supply adjacent opposite sides thereof respectively, and means for moving the stop carrying means and the stops vertically on the supports to various positions of adjustment thereon. 90
17. In a sheet feeder, means for supporting and advancing a supply of sheets standing on edge one behind another, stop means for engaging one or more front marginal portions of the supply, and means for elevating the front portion of the supply when it is moved into engagement with said stop means. 95
18. In a sheet feeder, means for supporting and advancing a supply of sheets standing on edge one behind another, and lifting means toward which the supply is advanced and adapted to elevate the front portion of said supply. 100
19. In a sheet feeder, means for supporting and advancing a supply of sheets standing on edge one behind another, mechanism for operating the sheet supporting and advancing means, and one or more detector elements rocking across one edge of the supply into and out of engagement with a front marginal portion thereof and controlling the operation of said mechanism and said means. 105
20. In a sheet feeder, means for supporting and advancing a supply of sheets standing on edge one behind another, mechanism for operating said means, control means for said mechanism, one or more detector elements rocking across one edge of the supply into and out of engagement with a front marginal portion thereof, and movable devices operated and controlled by said element or elements and controlling the operation of said control means. 115
21. In a sheet feeder, a plurality of separate means for supporting and advancing a supply of sheets standing on edge one behind another, a plurality of interconnected simultaneously actuated pawl and ratchet mechanisms for operating said means in unison, a plurality of rocking pawl masking elements controlling engagement of the pawls with and disengagement of the same from the ratchets, a rocking detector movable into and out of engagement with the front of the supply, and means operated by said detector and controlling the operation of said rocking pawl masking elements. 120
22. In a sheet feeder, means for supporting and advancing a supply of sheets standing on edge one behind another, means for successively separating and forwarding sheets from the front of said supply, mechanism for operating said first named means, and means controlling the operation of said mechanism and including one or more detector elements rocking across a front marginal portion of the supply into and out of engagement with the foremost sheet thereof. 125
23. In a sheet feeder, means for feeding a supply of sheets to be separated one after another, and detector means controlling movement of said first named means and the supply and movable interiorly across a marginal extremity of said supply after each sheet is separated therefrom. 130
24. In a sheet feeder, means for feeding a supply of sheets, and one or more detector devices controlling the movement of said means and the supply and movable interiorly and exteriorly across a marginal extremity of said supply once during each cycle of operation of said feeder. 135
25. In a sheet feeder, means for feeding a supply of sheets, means for separating sheets successively from the supply, and detector means controlling movement of said first named means and the supply and movable exteriorly of the supply across a margin of each sheet before it is separated from said supply. 140
26. In a sheet feeder, means for supporting and advancing a supply of sheets standing on edge one behind another, a follower for the supply, movable follower carrying means, and guide means for the follower carrying means adapted to prevent the weight of the supply from tilting the follower and said follower carrying means. 145
27. In a sheet feeder, a plurality of separate devices operated in one direction to support and feed a supply of sheets standing on edge one behind another, sheet separating means movable toward and away from the front of the supply to separate sheets successively therefrom, a plurality of interconnected pawl and ratchet mechanisms for simultaneously operating the supporting and feeding devices in said direction, and means for preventing retrograde movement of said devices and said supply during operation of said sheet separating means. 150
28. In apparatus of the character described, a plurality of separate means for supporting and feeding a supply of sheets standing on edge one behind another, a plurality of interconnected simultaneously actuated pawl and ratchet mechanisms for operating said means in unison, and reciprocating suction sheet separating means movable toward and away from the front of said supply to separate the sheets successively therefrom. 155
29. In apparatus of the character described, means to be fed, means for supporting and advancing a supply of sheets standing on edge one after another, and oscillating suction means for separating the sheets one after another from the front of said supply and for delivering them in like manner to said first named means. 160
30. In a sheet feeder, means for supporting and feeding a supply of sheets standing on edge 150

- one behind another, and a plurality of oscillating suction devices for separating the foremost sheet from the supply and having differential motion during part of their cycle of operation 5 to thereby buckle said sheet at the supply.
31. In a sheet feeder, means for supporting and feeding a supply of sheets standing on edge one behind another, and oscillating suction means for buckling the foremost sheet of the 10 supply and for separating and forwarding said sheet therefrom.
32. In a sheet feeder, means for supporting and feeding a supply of sheets standing on edge one behind another, and one or more oscillating 15 suction devices for buckling the foremost sheet of the supply successively in angularly related directions and for separating said sheet from said supply.
33. In a sheet feeder, means for supporting 20 and feeding a supply of sheets standing on edge one behind another, stop means for engaging the supply at the front thereof, and oscillating suction means for buckling the foremost sheet of the supply and for disengaging said sheet from said stop means and separating the sheet from said supply.
34. In a sheet feeder, means for supporting and feeding a supply of sheets standing on edge one behind another, means for separating and 25 forwarding the foremost sheet from the supply, and means for oscillating said sheet separating means about angularly related axes to separate and forward said sheet.
35. In a sheet feeder, means for supporting 30 and feeding a supply of sheets standing on edge one behind another, and a device movable vertically toward and away from the front of the supply and adapted to separate and forward the foremost sheet therefrom, said device being laterally movable within the margin of the sheet to engage it at the supply and laterally movable outwardly of said margin when the sheet is 40 separated and forwarded from said supply.
36. In a sheet feeder, means for supporting 45 and feeding a supply of sheets standing on edge one behind another, a plurality of separating devices, means for moving them toward and away from the supply to separate and forward the foremost sheet therefrom, and means for moving said sheet separating and forwarding devices toward and away from each other to engage the sheet at the supply and facilitate continued movement of said sheet after it has been separated and forwarded from said supply.
37. In a sheet feeder, means for supporting 50 and feeding a supply of sheets standing on edge one behind another, and one or more devices for separating sheets from the front of the supply, said device or devices acting to separate only one sheet at a time from the supply and push back any other sheet or sheets displaced forwardly thereof during the cycle of operation of the sheet separating device or devices.
38. In a sheet feeder, means for supporting 55 and feeding a supply of sheets standing on edge one behind another, stop means for the front of the supply, and means for separating sheets from the front of the supply, said sheet separating means acting to separate only one sheet at a time from the supply and push back any other portion thereof advanced past said stop means by said first named means.
39. In a sheet feeder, a plurality of oscillating 60 suction devices for separating a sheet from a supply and having differential motion during
- part of their cycle of operation to thereby buckle said sheet at the supply.
40. In a sheet feeder, oscillating suction means for both buckling a sheet of a supply and separating and forwarding said sheet bodily therefrom.
41. In a sheet feeder, one or more oscillating suction devices for buckling a sheet of a supply successively in angularly related directions and for separating said sheet from said supply.
42. In a sheet feeder, stop means for a supply of sheets, and oscillating suction means for buckling a sheet of the supply and for disengaging the sheet from said stop means and separating and forwarding said sheet from said supply.
43. In a sheet feeder, suction devices adapted to oscillate and separate a sheet from a supply, and means for swinging the suction devices into engagement with the sheet at the supply and for swinging said suction devices successively from the supply to buckle said sheet and separate it therefrom.
44. In a sheet feeder, a plurality of pivoted suction sheet separating devices, means for oscillating them to separate a sheet from a supply, and means for creating suction selectively in said devices at relatively different intervals during each cycle of operation thereof.
45. In a sheet feeder, a plurality of suction devices movable toward and away from a supply of sheets and adapted to separate a sheet therefrom, and means for creating suction successively in the suction devices upon movement of the same toward the supply and for breaking the suction successively in said devices when they move away from the supply and have separated said sheet therefrom.
46. In a sheet feeder, a plurality of suction sheet separating devices, a source of suction, connections between said source and the sheet separating devices, automatically operated main control means interposed in the connections, and automatically operated auxiliary control means interposed in said connections between said main control means and said sheet separating devices.
47. In a sheet feeder, sheet separating means movable about angularly related axes, and means for swinging said sheet separating means in opposite directions about said axes at predetermined intervals.
48. In a sheet feeder, a pair of sheet separating devices, means for swinging them toward and away from the sheet supply, and means for swinging said devices toward and away from each other.
49. Separating a sheet from a supply by buckling the sheet crosswise and lengthwise successively in a desired order and moving said sheet away from said supply.
50. Separating a sheet from a supply by buckling the sheet crosswise and lengthwise successively in a desired order and swinging said sheet away from said supply.
51. Separating a sheet from a supply by forming a buckle in the sheet and forming another buckle in the sheet eliminating the first buckle and extending in a direction transversely of that in which said first buckle was formed.
52. Separating a sheet from a supply by forming one or more buckles therein extending in one direction, forming another buckle in the sheet eliminating the first buckle or buckles and extending in a direction transversely of the direction of formation of said first buckle or

- buckles, and moving said sheet bodily away from said supply.
53. In a sheet feeder, curved means arranged in spaced parallel relation and to convex portions of which a sheet is fed, and oscillating means for separating the sheet from the front of a supply and delivering the sheet to the curved means, said oscillating means moving within the arc of curvature of said curved means upon delivery of the sheet to said convex portions thereof.
54. In a sheet feeder, driven endless sheet conveying means arranged in spaced parallel relation, and oscillating suction sheet separating and forwarding means adapted to deliver a sheet to said sheet conveying means and movable past the latter to facilitate advancement of the sheet thereby.
55. In apparatus of the character described, means to which sheets are fed, sheet supporting means curved downwardly and rearwardly thereof, and an endless conveyor guided in a curved path on the sheet supporting means and adapted to move a sheet upwardly and forwardly thereover for delivery to said first named means.
56. In apparatus of the character described, a frame having curved anti-friction sheet supporting surfaces extending thereover in spaced relation from a rear bottom portion of said frame to a front top portion thereof, and means on the frame for advancing a sheet upwardly and forwardly along said surfaces.
57. In apparatus of the character described, a frame having marginal surfaces in spaced relation, anti-friction sheet supporting means on said surfaces, guide means extending along the frame adjacent the anti-friction sheet supporting means, and means movable along said guide means for pushing a sheet along said anti-friction sheet supporting means.
58. In apparatus of the character described, a frame provided with curved sheet supporting means, guide means on the frame co-extensive with the curved sheet supporting means and curved in conformity therewith, endless means adapted to travel on said guide means, and devices secured to said endless means at intervals along the same and adapted to push sheets successively along said curved sheet supporting means.
59. In apparatus of the character described, feed and drop rollers, sheet guiding means inclined forwardly and downwardly thereto, and rocking fingers adapted to engage the rear edge of a sheet and push said sheet over said sheet guiding means to said rollers.
60. In apparatus of the character described, means to which sheets are fed, driven endless sheet advancing means, mechanism for delivering a sheet to said driven endless sheet advancing means, and mechanism adapted to move the sheet with continuously accelerated speed from the driven endless sheet advancing means to said first named means.
61. In apparatus of the character described, means to which sheets are fed, sheet supporting means curved thereto, an endless conveyor guided in a curved path on the supporting means and adapted to advance the sheets thereon, and rocking fingers adapted to engage the rear edge of the sheet and move it with accelerated speed from the conveyor and the curved sheet supporting means to said first named means.
62. In a sheet feeder, sheet feeding means, a member for cooperating therewith to feed a supply of sheets, operating mechanism for the member adapted to be connected with and disconnected from the same, loading means movable longitudinally of the sheet feeding means to deliver the supply of sheets thereto, and means providing for movement of the member relative to its operating mechanism when disconnected therefrom, whereby said member may be engaged with the supply of sheets and thereafter connected with said mechanism to cooperate with said sheet feeding means in feeding said supply.
63. In a sheet feeder, sheet feeding means, a member for cooperating therewith to feed a supply of sheets, operating mechanism for the member adapted to be connected with and disconnected from the same, loading means movable longitudinally of the sheet feeding means to move the supply of sheets in position for delivery thereto, means providing for movement of the member relative to its operating mechanism when disconnected therefrom whereby said member may be engaged with the supply of sheets and thereafter connected with said mechanism to cooperate with said sheet feeding means in feeding said supply, and means on said loading means for delivering the supply of sheets to the sheet feeding means when the member has been engaged with the supply of sheets and connected with said operating mechanism.
64. In a sheet feeder, sheet feeding means, a member for cooperating with the sheet feeding means to feed sheets carried thereby, operating mechanism for the member adapted to be connected with and disconnected from the same, loading means movable longitudinally of the sheet feeding means to deliver additional sheets thereto, means providing for movement of the member relative to its operating mechanism when disconnected therefrom, whereby said member may be engaged with the additional sheets and thereafter connected with said mechanism to cooperate with the sheet feeding means in feeding all of the sheets, and means for temporarily connecting the loading means with the sheet feeding means to feed all of the sheets until the member has been engaged with the additional sheets and connected with said operating mechanism.
65. In a sheet feeder, sheet feeding means, a member movable with and independently of the sheet feeding means to engage and assist in feeding sheets delivered thereto and fed thereby, loading means movable longitudinally of the sheet feeding means to deliver the sheets thereto, and retaining means movably mounted on the loading means to retain the sheets thereon and release them for delivery to the sheet feeding means when said member has been engaged with said sheets.
66. In a sheet feeder, sheet feeding means, a slotted member movable with and independently of the sheet feeding means to engage and assist in feeding sheets delivered thereto and fed thereby, loading means movable longitudinally of the sheet feeding means to deliver the sheets thereto, sheet retaining means on the loading means and over which the slotted member extends when it is initially engaged with the sheets, and means for operating the retaining means to move the same through the slots of said member and release the sheets.
67. In a sheet feeder, means for supporting and feeding a supply of sheets, sheet conveying

- means to which sheets are delivered one after another from said supply, means for separating sheets successively from one extremity of the supply and for delivering them in like manner 5 to said sheet conveying means, and means for adding sheets to the supply at the opposite extremity thereof.
68. In a sheet feeder, mechanism for supporting and feeding a supply of sheets, sheet conveying means to which sheets are delivered one after another from said supply, means for separating sheets successively from one extremity of the supply and for delivering them in like manner 10 to said sheet conveying means, and means for adding sheets to the supply at the opposite extremity thereof during operation of said mechanism and said first named means.
69. In a sheet feeder, means for supporting and feeding a supply of sheets standing on edge 15 one behind another, sheet conveying means to which sheets are delivered one after another from said supply, means movable toward and away from the front of the supply for separating sheets successively therefrom and delivering them in like manner to said sheet conveying means, and means for adding sheets to the supply at the rear thereof.
70. In a sheet feeder, mechanism for supporting and feeding a supply of sheets standing on edge 20 one behind another, sheet conveying means to which sheets are delivered one after another from said supply, means movable toward and away from the front of the supply for separating sheets successively therefrom and delivering them in like manner to said sheet conveying means, and means for adding sheets to the supply at the rear thereof during operation of said mechanism and said first named means.
71. In a sheet feeder, means for supporting and feeding a supply of sheets standing on edge 25 one behind another, and loading means movable longitudinally of said first named means to deliver said supply thereto.
72. In a sheet feeder, means for supporting and feeding a supply of sheets, and loading means movable relative to said first named means to deliver said sheets thereto standing on edge one behind another.
73. In a sheet feeder, sheet feeding means, a carriage movable longitudinally of the sheet feeding means to a position for delivery of sheets thereto, and sheet supporting means on the carriage movable thereon to deliver the sheets to said sheet feeding means when said carriage has 30 been moved to said position.
74. In a sheet feeder, sheet feeding means, and loading means movable longitudinally of the sheet feeding means and adapted to position sheets for delivery thereto from a level higher than that of sheets thereon.
75. In a sheet feeder, sheet feeding means, loading means movable longitudinally of the sheet feeding means and adapted to position sheets for delivery thereto from a level higher than that of sheets thereon, and means for lowering the sheets from the loading means onto said sheet feeding means.
76. In a sheet feeder, sheet feeding means, loading means movable longitudinally of the sheet feeding means to deliver sheets thereto, and means on said loading means for clamping sheets thereon.
77. In a sheet feeder, sheet feeding means, a device for receiving a supply of sheets, and means providing for movement of said device 35 in one direction to receive the sheets and in the opposite direction to position said sheets for delivery to said sheet feeding means.
78. In a sheet feeder, sheet feeding means, and loading means mounted on and movable along the feeder adjacent the sheet feeding means and adapted to deliver a supply of sheets thereto standing on edge one behind another.
79. In a sheet feeder, sheet feeding means, a carriage mounted on and movable along the feeder adjacent the sheet feeding means, and means mounted on and movable on said carriage for receiving a supply of sheets and delivering the same to said sheet feeding means.
80. In a sheet feeder, sheet feeding means, a carriage mounted on and movable along the feeder adjacent the sheet feeding means, and oscillatory means on the carriage for receiving a supply of sheets and delivering the same to said sheet feeding means.
81. In a sheet feeder, sheet feeding means, and loading means therefor adapted to swing a pile of sheets from a horizontal position to a vertical position so that the sheets stand on edge one behind another for loading on and 40 feeding by said sheet feeding means.
82. In a sheet feeder, sheet feeding means, and loading means mounted for swinging movement in opposite directions to receive the sheets and position them for delivery to said sheet feeding means.
83. In a sheet feeder, sheet feeding means, and pivotally mounted means movable in one direction to receive sheets piled one on another and movable in the opposite direction to turn 45 the sheets whereby they stand on edge one behind another for delivery to said sheet feeding means.
84. In a sheet feeder, sheet feeding means, loading means mounted on and movable along the feeder in opposite directions to receive sheets at one end of said feeder and transport them toward the opposite end thereof for delivery to said sheet feeding means, and means for moving the loading means as aforesaid.
85. In a sheet feeder, sheet feeding means, a movable carriage on the feeder, sheet holding means pivoted on the carriage to receive sheets when the carriage is moved in one direction and deliver them to said sheet feeding means when the carriage is moved in the opposite direction, and means for swinging said sheet holding means in opposite directions to receive and deliver the sheets respectively.
86. In a sheet feeder, sheet feeding means, a movable carriage on the feeder, means for moving the carriage in opposite directions, sheet holding means mounted on the carriage to receive sheets when the carriage is moved in one direction and deliver them to said sheet feeding means when said carriage is moved in the opposite direction, and means for moving said sheet holding means in opposite directions to receive and deliver the sheets respectively.
87. In a sheet feeder, sheet feeding means, a device over which a supply of sheets may be positioned for delivery to the sheet feeding means and means for swinging said device in opposite directions to receive and deliver the sheets.
88. In a sheet feeder, sheet feeding means, sheet supporting means over which a supply of sheets may be positioned by a truck, and means for reciprocating and oscillating said device to 50

remove the sheets from the truck and deliver them to said sheet feeding means.

89. In a sheet feeder, sheet feeding means, a device over which a supply of sheets may be positioned by a truck, a carriage for moving the device in opposite directions to receive the sheets from the truck and transport them for delivery to the sheet feeding means, mechanism for moving the carriage and the device in opposite directions, and mechanism for swinging the device in opposite directions to receive and deliver the sheets respectively.

90. In a sheet feeder, sheet feeding means, pivotally mounted loading means movable in one direction to receive a supply of sheets stacked one above another, and means for connecting the loading means with the sheet feeding means to swing the latter and the sheets in the opposite direction whereby said sheets are turned into standing position one behind another for delivery to said sheet feeding means.

91. In a sheet feeder, sheet feeding means, a device movable longitudinally of the sheet feeding means to deliver sheets thereto, and means

movable in one direction to clamp or gather the sheets on said device and movable in the opposite direction to deliver the sheets therefrom to said sheet feeding means.

92. In a sheet feeder, sheet feeding means, loading means therefor having rollers, and guide means for said rollers whereby the loading means may be moved along said sheet feeding means.

93. In a sheet feeder, loading means therefor having rollers, guide means for said rollers whereby the loading means may be moved along the feeder, and depressions in the guide means to receive the rollers and prevent accidental displacement of the loading means.

94. In apparatus of the character described, sheet feeding means, portable loading means therefor movable into and out of operative relation therewith, and sheet holding means on said portable means movable therefrom along the sheet feeding means to deliver sheets thereto when said portable means is moved into operative relation therewith.

remove the sheets from the truck and deliver them to said sheet feeding means.

89. In a sheet feeder, sheet feeding means, a device over which a supply of sheets may be positioned by a truck, a carriage for moving the device in opposite directions to receive the sheets from the truck and transport them for delivery to the sheet feeding means, mechanism for moving the carriage and the device in opposite directions, and mechanism for swinging the device in opposite directions to receive and deliver the sheets respectively.

90. In a sheet feeder, sheet feeding means, pivotally mounted loading means movable in one direction to receive a supply of sheets stacked one above another, and means for connecting the loading means with the sheet feeding means to swing the latter and the sheets in the opposite direction whereby said sheets are turned into standing position one behind another for delivery to said sheet feeding means.

91. In a sheet feeder, sheet feeding means, a device movable longitudinally of the sheet feeding means to deliver sheets thereto, and means

movable in one direction to clamp or gather the sheets on said device and movable in the opposite direction to deliver the sheets therefrom to said sheet feeding means.

92. In a sheet feeder, sheet feeding means, loading means therefor having rollers, and guide means for said rollers whereby the loading means may be moved along said sheet feeding means.

93. In a sheet feeder, loading means therefor having rollers, guide means for said rollers whereby the loading means may be moved along the feeder, and depressions in the guide means to receive the rollers and prevent accidental displacement of the loading means.

94. In apparatus of the character described, sheet feeding means, portable loading means therefor movable into and out of operative relation therewith, and sheet holding means on said portable means movable therefrom along the sheet feeding means to deliver sheets thereto when said portable means is moved into operative relation therewith.

ROSS MEREDITH.

DISCLAIMER

1,982,823.—*Ross Meredith, Pearl River, N. Y. SHEET FEEDING MACHINE. Patent dated December 4, 1934. Disclaimer filed March 30, 1936, by the assignee, Dexter Folder Company.*

Hereby enters this disclaimer to claims 1, 2, 29, 37, and 38 in said specification.
